UNITED STATES PATENT OFFICE

2,678,206

INDICATING AND PRINTING DEVICE

William J. Muldoon, Garden City, and Arthur L. Thurston, Wantagh, N. Y., assignors to Cox and Stevens Aircraft Corporation, Mineola, N. Y., a corporation of New York

Application June 22, 1949, Serial No. 100,652

14 Claims. (Cl. 265—5)

1
This invention relates to an indicating and printing device, and more particularly to an automatic force measuring device wherein forces such as those due to weight are automatically indicated and a printed recording made thereof.

The indicating and printing device comprising this invention is adapted for working in conjunction with force or weight measuring cells which are described in copending United States patent application Serial No. 539,658, filed June 10, 1944, by Arthur L. Thurston, now United States Patent No. 2,488,349.

In the measuring of large forces, as in the weighing of heavy loads, for example, the weighing of livestock in stockyards, groups or drafts of individuals are weighed upon a large platform, there being possibly 500 to 600 separate drafts or weighings in a day upon a single scale. The ownership of the livestock in normal practice changes hands when weighing takes place and it is usual procedure for the weight of each draft or group of livestock to be printed on a ticket with one or more carbon copies. Usually the weigh master writes in longhand on the ticket the name of the owner, the name of the buyer and then his signature. He also may write in longhand the number of livestock or cattle, the species and other data as required by the specific stockyard. This is a time consuming and thus an expensive activity. When the name of the owner and the name of the buyer are the same for several successive weighings or drafts of livestock, the data above mentioned have in the past been marked on separate tickets or cards and the weigh master has thus been required to write such data and to sign his name several times. It is estimated that one-quarter to one-third of the weigh master's time has in the past been spent in signing his name. This invention provides a means for automatically printing one, two or three successive sets of information including weight on the same ticket, each for a separate draft of livestock, and provision is made also by printing means for stamping a facsimile signature of the weigh master once upon such ticket, thereby saving considerable time. If desired only one set or line of information need be printed.

Also novel means are provided for automatically printing upon such ticket the weights of the individual drafts of livestock.

Furthermore, in weighing devices for weighing large loads, such as drafts of livestock, the indicating device has of necessity been located closely adjacent the weighing platform when in many

instances it is desirable to locate it in a remote position. This is also true of the device for printing the indication of the weights of the drafts.

5 Furthermore, weighing devices for large loads heretofore suggested have usually employed knife edges in conjunction with a platform. Such knife edges very often become dulled due to severe fibre stresses and wear requiring frequent replacement and servicing.

10 In weighing livestock, it is necessary frequently to balance the scale mechanism when it is empty of the livestock. This in the past has been done manually and is normally referred to as manually adjusting scale zero for tare. The weight of the platform in a livestock scale changes due to the droppings left by the cattle on the platform and necessitates frequent rebalancing or adjusting scale zero for tare. In making such manual adjustment on scales heretofore proposed, there is a possibility of the weigh master erring so that the scales weigh "light" and, of course, there is always the possibility of a weigh master making a deliberate error when making such adjustment. On some types of livestock scales, on a busy day between 700,000 and 900,000 lbs. of livestock may be weighed on a single scale in, for example, 500 to 600 different weighings. It is usual for such livestock to be sold through commission merchants by a large number of owners to a relatively small number of buyers. If, through mistake or collusion between the buyers and the weigh master, the latter balances the scale to read, for example, 5 lbs. light at each draft, which is not difficult to do without detection on the usual type of scale, this would make a difference of from 2500 to 3000 lbs. during the day in favor of the buyers. Such error in the scale may result in an underpayment of the sellers to the extent of many hundreds of dollars per day.

15 Furthermore, no accurate electronic scales has been heretofore suggested which provides a rapid visual indication of weight together with rapidly actuatable weight indicia for the printing of such weight upon a card.

20 One of the objects of the present invention is to overcome the above difficulties or to reduce same to insignificance.

25 The invention in one aspect thereof is constituted by a force measuring or weighing device having in combination a force or weight sensitive cell means employing force or stress receiving column means, the latter carrying electrical resistance type strain gauge means bonded

thereto. The latter means are connected in an electrical circuit for measuring a change in an electrical characteristic of such means in response to stress received by said column means, that is, a force or weight signal is produced responsive to such stress. Such change in electrical characteristic is employed for controlling a servomotor in conjunction with a so-called null or balancing circuit wherein the signal from the cells is balanced against a signal controlled by the servomotor. The servomotor is initially under the influence of the above-mentioned change in electrical characteristic, and the motor, by being operatively associated with the balancing circuit, establishes a null condition, thereby arresting the servomotor after a movement thereof which is responsive to the change in such electrical characteristic. The servomotor is operatively associated with a remotely located stress or force indicia including a device having a first portion for coarse indications of the movements of the servomotor, and a second portion for fine indications of such movements. Novel means are provided for operatively interconnecting such servomotor and stress indicia device comprising two separate self-synchronous repeater systems, the transmitters of which are driven by said motor in a preselected speed ratio to provide separate fine and coarse transmitter movements. The receivers of the self-synchronous repeater system are respectively connected to the fine and coarse stress indicia devices whereby the coarse repeater system is capable of driving the coarse stress indicia in tracking or repeating relationship throughout its range of movement, and the fine repeater system actuated in response to fine indications of the force signal, due to the high speed of such latter repeater system, loses synchronization due to its inability to follow the high speed of its transmitter whereby the fine stress or force indicia does not track the high speed or fine repeater transmitter but moves into step and synchronizes with such transmitter a fraction of a second after the servomotor comes to rest.

Novel means are provided for adjusting a visual indicator controlled by the servomotor in order to account for residual forces or stresses upon the force measuring cells, for example, residual weights which may be upon such cells. Such visual indicator can be separate from said stress indicia above mentioned. Such novel means comprises a second servomotor also referred to as a zero adjusting motor which is actuated in response to the departure of the fine transmitter of the fine synchronous repeater system when the main load upon the force measuring cells has been removed. Such zero adjusting motor is drivably connected with such fine transmitter for returning same to an initial zero position whereupon the zero adjusting motor is stopped.

The above and further objects and novel features will more fully appear from the detailed description when the latter is read in connection with the accompanying drawings. It is to be expressly understood that the drawings are for purposes of illustration only and are not intended as a definition of the limits of the invention, reference for this latter purpose being had to the appended claims.

In the drawings:

Fig. 1 is a perspective view of a weight indicator and an automatic printing device used in

conjunction with a plurality of weighing cells upon which rests a weighing platform, the combination embodying one aspect of the invention;

Fig. 2 illustrates a so-called scale ticket upon which the printing device records certain information desired in the weighing of livestock as at a stockyard;

Fig. 3 is a schematic wiring diagram showing one plan for electrically interconnecting the weighing cells, the indicator and the printing device, together with certain other parts of the apparatus;

Fig. 4 is another schematic wiring diagram, with certain parts omitted for clarity, illustrating the electrical interconnection between the force measuring cells, a visual indicator and a servomotor, together with certain elements for controlling the electrical signal to such motor in accordance with one form of the invention;

Fig. 5 is a graphic representation of the voltage output of the circuit of the force measuring cells under the influence of a so-called "dead load" and of a "moving load," the latter creating random accelerations;

Fig. 6 is a schematic wiring diagram illustrating in greater detail the electrical circuits shown schematically in Fig. 4;

Fig. 7 is a schematic view in perspective, with certain parts omitted for purposes of clarity, illustrating the operative interconnection between a main servomotor and the visual indicator employed in the present invention, together with the motor for adjusting the scale to zero for tare weight;

Fig. 8 is an enlarged perspective view of a mechanical limit stop device employed with the parts shown in Fig. 7;

Fig. 9 is a perspective view of the printing device employed in one embodiment of the present invention with the top portion thereof angularly shifted to an open position, and with a lower front cover thereof removed from its normal position thereby illustrating certain of the elements within the housing of the device;

Fig. 10 is a view similar to Fig. 9, with certain of the parts eliminated for purposes of clarity, such as a carbon ribbon and a supporting shelf therefor and revealing additional parts of the mechanism;

Fig. 11 is a vertical cross-sectional view, with certain parts omitted, showing portions of the printing device illustrated in Figs. 9 and 10;

Fig. 12 is a front view of a group of co-acting type wheels having numerals embossed upon the peripheries thereof and employed for printing weights upon the scale ticket shown in Fig. 2;

Fig. 13 is a schematic view in perspective showing the mechanical interconnection between certain of the type wheels shown in Fig. 12 and the motor drive means therefor;

Fig. 14 is also a perspective schematic view of the mechanical interconnection between the remaining type wheels and motor drive means therefor, such remaining type wheels being driven at a speed relatively slower than the type wheels shown in Fig. 13;

Fig. 15 is a view illustrating how the type wheels of Fig. 12 might print upon a scale ticket in the absence of type wheel aligning means;

Fig. 16 is an exploded view in perspective of the type wheels of Fig. 12, together with a wheel aligning mechanism embodying a modification of the present invention;

Fig. 17 is a transverse sectional view of a gear element employed in both of the gear trains, as

shown in Figs. 13 and 14, for facilitating alignment of the type wheels and also the making of an initial adjustment thereto;

Fig. 18 is a side view partly in section and with parts broken away of the gear element shown in Fig. 17;

Fig. 19 is a transverse sectional view of a type wheel and cam employed in the group of type wheels of Figs. 12 and 16;

Fig. 20 is a side elevation of the type wheel and cam of Fig. 19;

Fig. 21 is a side view of an indexing or aligning finger employed in the aligning mechanism shown in Fig. 16;

Fig. 22 is a plan view of the finger shown in Fig. 21;

Fig. 23 is a transverse sectional view taken through a front portion of the printing device and illustrating a ticket holding and indexing mechanism employed in the present invention;

Fig. 23a is a perspective view of a pair of notched disk members employed in the ticket indexing mechanism;

Fig. 24 is a sectional view taken substantially along line 24—24 of Fig. 23.

Fig. 25 is a side view of a cam mechanism viewed along line 25—25 of Fig. 24;

Fig. 26 is a side elevation of a platen or hammer device employed in the printing device;

Fig. 27 is a plan view of the parts shown in Fig. 26;

Fig. 28 is a front elevation of a carbon ribbon pulling or operating mechanism; and

Fig. 29 is a side view of the mechanism shown in Fig. 28.

In the form of the invention shown in Fig. 1, the apparatus is designed for the weighing of livestock upon a platform or weighbridge 50 which can be rectangular and which is shown supported, for example, upon four weighing cells 51 located beneath the respective corners of the platform. The weighing cells are connected by suitable electrical conduits as at 52 to a visual weight indicating device 53 also referred to as an indicator unit and having a housing 54. The latter unit is electrically connected as by conduit 55 to a printer unit 56. A suitable source of electric energy is connected to the apparatus by a power cable 57 which is directed into the indicator unit 53. The source of electric energy can constitute, for example, 110 volts 60 cycle A. C.

The above-mentioned indicator unit 53 is, in the form shown, of a visual character but, of course, within the purview of this invention any other type of signal indicator may be employed as an alternative, and it is not essential to employ any indicator of the character as at 53. The signal responsive to weight can be sent directly to the printer 56 for an indication thereof as will be explained more fully herebelow.

The housing 54 for the visual indicator 53, as shown in Fig. 1, also provides a housing for certain of the elements of the electrical circuits shown in Fig. 3, also to be explained below. The visual indicator proper comprises a dial 53 on which there are calibrated two separate scales 59 and 60 comprising respectively coarse and fine calibrations. Suitable pointers are provided for cooperating with the scales, such as coarse pointer 61 and fine pointer 62. Such pointers are operatively interconnected to move in a preselected speed ratio, for example, 50 to 1. That is, when the coarse pointer moves one revolution, the fine pointer moves fifty revolutions.

A scale which is capable of measuring loads up

to 50,000 lbs. is considered suitable for normal use in weighing loads such as drafts of livestock and the two scales upon dial 53 are calibrated to indicate loads from zero up to such a maximum. The coarse or inner scale is graduated in 1,000 lb. increments from 0 to 50 and the outer scale is graduated in, for example, 10 lb. increments from 0 to 1,000 lbs. The pointers and their control mechanism are adjusted so that both will indicate zero, for example, when they are pointed upward in vertical position. Thus the form of the visual indicator herein employed gives an indication of weight in a manner analogous to the hour and minute hands of a clock and can be readily observed by a weigh master.

The scale ticket, which is shown in Fig. 2 as at 63, has been designed for recording the information desired, for example, in the weighing of livestock, and includes a main column 64 in which on successive lines the weight of a plurality, such as three, of separate successive drafts of livestock can be recorded. The recording of such weights is made in column for a purpose which will appear hereinafter, and the recording of other items of information is also made in column. The printing mechanism for printing the weight is automatically set by means to be explained in detail below. There are provided additional columns, for example, columns 65, 66 and 67 which are respectively for recordings of the time of weighing (year, month, date, a. m. or p. m., hour and minute); scale number; and livestock draft number. The mechanism for printing in the last three mentioned columns 65, 66 and 67 is automatically set by the printing device without assistance by the weigh master. Additional columns are provided as at 68, 69, 70 and 71 wherein information is printed which may be manually set by means of suitable knobs upon the printing device 56. In these columns (68, 69, 70, 71) there are indicated, for example, respectively (a) species of the livestock, (b) the number of livestock in the particular draft, (c) the name or symbol of the commission agent, and (d) the price.

Space is provided, as at 72, for the printing of the signature of the weigh master. This is accomplished by a metal slug having embossed thereon the signature of the weigh master which slug is removably positioned in the printing device 56, as will be explained below.

Preferably the means for printing the scale number or scale designation for column 66 is set in the mechanism at the time of its manufacture so that of the mechanisms for printing in columns 65, 66 and 67 only the first and last mechanisms require automatic setting.

While the data recordable upon the ticket 63 are particularly adapted for the weighing of livestock, it is, of course, understood that the invention is not limited thereto and that other data can be printed as desired.

The species of livestock is set manually on the printer 56 by manual adjustment of a knob 68a. The number of individuals is indicated by adjustment of the two handles 69a and 69b, one for each digit. Normally drafts of livestock are less than ninety-nine individuals and consequently it is usually unnecessary to employ more than two digits for columns 69. The symbol of the commission agent for column 70 is manually set by adjusting the knobs 70a and 70b. If desired, an automatic mechanism, which is operatively connected with the weight indicator, can calculate the price in response to the weight and indicate same in column 71 but in the particular embodiment

ment shown, no provision is made for printing in this column. The mechanism for setting the type for printing in columns 68—70, inclusive, is comparable to the mechanism used in a conventional check-writing device.

The scale ticket 63 is inserted into the printer for printing by means of a manually controlled clamping device in the form, for example, of a hinge clamp 73 which is resiliently urged to a closed position by means of a spring 74 wound about a pivot pin of the hinge. A handle for opening such hinge clamp is indicated at 75 and is rigidly secured to the top portion thereof. Suitable fingers are secured to the bottom portion of the hinge and extend down into the housing of the printing device through slots 76 and 77, as will be explained more fully hereinafter, whereby the hinge is held in accurate alignment with the printing mechanism and is adapted for being advanced by increments into the printing machine for the printing of the above-described data successively on the horizontal lines 63a, 63b and 63c, each line representing a separate draft of livestock. Such lines are also referred to as lines (1), (2) and (3), respectively. Although there may be three separate lines of data printed upon the scale ticket, the signature of the weigh master in space 72 is printed only once, namely, when the information on the first line, 63a, is printed. Thereafter suitable means are provided for rendering inoperative the facsimile signature printing means, as will be explained below.

Printer device control elements (weigh master's controls)

The controls which are operable by the weigh master are all preferably located on the printing device 56, as shown in Fig. 1, and they consist of manually operable switches as of the push button and toggle type as follows:

(1) An "on-off" toggle switch 78 which provides a master control switch for the electrical energy to the entire apparatus, as illustrated, for example, in Fig. 3.

(2) A normally open push button switch 79 marked zero which is actuated in order to adjust the scale 58 zero indication for tare. That is, if the weight of the platform after emptied of livestock changes from zero, as it will due to, for example, the droppings of the livestock, so that the pointers 61, 62 fail to return to "0," a momentary closing of this switch by pressing its button will actuate automatic means to be described in detail hereinafter for causing such pointers to return to "0" on their scales. This being an automatic adjustment, the possibility is eliminated of the weigh master making a mistake in such adjustment inadvertently or by design.

(3) A toggle switch 80 which is marked "Fast" and "Slow," which in the "Fast" position permits the visual indicator and certain printing indicia associated therewith to move at maximum speed, and in the "Slow" position slows the response of such indicator and printing indicia, and imposes a predetermined dampening upon the apparatus in order to minimize any oscillations of the pointers 61 and 62 and/or the means for controlling same, which oscillations normally are due to the milling or stamping of the cattle. Such oscillations are usually referred to as the result of random accelerations due to random loads upon the weighing platform.

(4) A toggle switch 81 marked "Run" and "Stop" which in the former position allows a nor-

mal operation of the apparatus wherein the pointers 61, 62 indicate, by means of the novel apparatus, whatever weight is put on the platform 50, and in the "Stop" position arrests the indicator control apparatus and locks such pointers in whatever position they may be when the switch is closed. In weighing livestock, this is used in order to give the weigh master time to read the scale should he require it. This control allows the weigh master to stop the indicating pointers when the livestock are weighed, to count the individuals and thereafter manually adjust the knobs 69a, 69b to indicate such count before he actuates the printing mechanism for printing the scale ticket 63. This control is also of advantage when weighing a series of objects or drafts of livestock of about the same weight. For example, after one draft of livestock is weighed, the switch 81 is moved to "Stop," the livestock removed from the platform and replaced by a second draft or by a second object, whereupon the stop switch is moved to the "Run" position and the second draft or object is weighed. Thus it is not necessary for the pointers 61, 62 to return to "0" in between weighings. This saves time and also minimizes wear on the equipment. A further advantage of this stopping feature is found in connection with a fast moving load which may be on the platform only for a very short time, such time normally not being sufficient to permit the weigh master to observe the indicator 53 and to actuate the printing mechanism.

(5) A control switch 82 is provided for controlling the printing mechanism and in the form shown is of a conventional push button variety which is normally in an open condition. The momentary closing of this switch by the pressing of its button starts the printing cycle. Once the switch 82 is closed momentarily, the printing cycle is automatically completed within a very short time interval, for example, about three-quarters of a second, by means to be described below.

(6) A single glow lamp 83 is so connected into the electric circuit of the apparatus that it lights only when a scale ticket 63 is in position to print either line (1), (2) or (3). The main function of this light is to indicate to the weigh master, when it goes out, that all of the lines of the ticket have been printed and that such ticket must be removed and a new one inserted.

Referring again to Fig. 1, the ticket holder or hinge clamp 73 is withdrawn from a position for printing, as shown in this figure, manually by grasping the handle 75 and pulling it as far as it will go, whereupon the handle is pressed downwardly to open same. The weigh master thereupon can insert a scale ticket within the open hinge clamp, and in order to position the ticket accurately urges it against a guide member 73a at the left of the hinge. Thereupon the handle 75 can be released. The ticket is thus clamped in the hinge and the weigh master then can push the ticket holder away from him, as viewed in Fig. 1, as far as it will go, which inserts the ticket in the printing device in position to print line (1). In this position a reference mark, for example, an extremity of the hinge pin, is positioned opposite a numeral(1), as shown upon an index plate 73b. After a draft of livestock has been moved upon the weighing platform 50, the indicator 53 and the weight printing indicia of the printing device are actuated. Then the print switch or button 82 is pressed, and the desired data are printed in line

(1). Thereafter, the hinge clamp or ticket holder 73 is automatically advanced or "indexed into position" for the printing of line (2). When the ticket holder is in position for the printing of lines (2) and (3), the hinge pin thereof is opposite the numerals (2) and (3), respectively, upon the plate 73b. After printing line (2), the ticket holder again is automatically advanced for the printing of line (3). After line (3) has been printed, the print switch 82 becomes inoperative, whereby no more printing can be done until the ticket is removed and a new one inserted. The mechanism for accomplishing the above will be described hereinafter. During the time that ticket holder 73 is in printing positions (1), (2) or (3) the lamp 83 is lighted indicating that the power means for the printing mechanism can be actuated by pushing button 82. After line (3) has been printed, lamp 83 is extinguished.

Circuit description—System schematic

Referring now to Figs. 3, 4, 5 and 6, there will now be described the electrical interconnections between the various parts of the novel apparatus, and also pertinent portions of the mechanical interconnections therebetween.

In general, the apparatus comprises a force sensitive device which, in the form shown, is designed for sensing weight and is constituted by the above-described weighing cells 51 which when subjected to a stress provide an electrical signal output which is proportional to said stress, the output in the embodiment illustrated being constituted by a voltage. This voltage controls a signal responsive means such as a servo or control motor 84 through the intermediary of a so-called null system or null control means of which the servomotor is a part. The electrical voltage output of the cells 51 is exceedingly small and must be highly amplified and controlled in a manner to be described in detail hereinafter by means which are illustrated schematically in Fig. 4.

The above-mentioned null system employs as its main element a means for introducing a counter or balancing signal for balancing the cell signal, such means comprising, for example, a slide wire resistance indicated generally at 85 which is under the influence of the servomotor 84 by means of a suitable operative interconnection which, in the form shown, is a mechanical one. The slide wire resistance 85 is so connected into the circuit of the weighing cells 51 that a counter E. M. F. or balancing voltage may be introduced into such circuit and a null condition can thereby be produced which will be attained when the servomotor 84 has been actuated to an extent proportional to the signal output of the weighing cells 51.

A so-called oscillator-amplifier is employed which is schematically indicated at 86 in Fig. 3 and illustrated in greater detail in Figs. 4 and 6. This device provides a voltage of carrier frequency for the cells and is employed for amplifying the output voltage of such cells.

Means are provided for converting such electrical output into the motion of an indicator which is linearly proportional to weight. Suitable electrical means to be described hereinafter are provided for accomplishing this. In the form shown, the control or servomotor 84 is operatively associated with a remote signal responsive means such as a weight digital printer which is a part of the printing device 56. The operative interconnection between such servo-

motor and the weight digital printer permits a remote indication of the weight for the printing thereof within a negligible or substantially no additional time after the servomotor 84 has stopped after adjusting said slide wire element 85 to a null condition. In the form shown, the apparatus is designed for registering loads up to 50,000 lbs. within a time limit of three seconds. This means that the servomotor 84 and the pointers 61, 62 move from zero up to 50,000 lbs. on dial 58 within three seconds. The remote indicator, for example, the weight digital printer, is prepared for registering such maximum load substantially simultaneously with the time that such pointers reach this mark.

A portion of such weight digital printer is shown in Fig. 3 as at 87, and comprises, for example, a plurality of so-called type wheels having embossed upon their peripheries numerals for indicating the weight which is also registered upon the dial 58. The type wheels 87 are divided into two groups 87a and 87b for a purpose to appear more fully hereinafter and each group of type wheels is driven by a separate means, that is, there is one operative interconnection between wheels 87a and the control motor 84 and a separate operative interconnection between group 87b and such motor.

The movement of the servomotor 84 is, as above described, indicated upon the dial 58 by means of coarse and fine pointers 61, 62. The groups of type wheels 87a and 87b respond respectively to such coarse and fine indicators. Due to the extreme speed at which it is necessary for the fine pointer 62 to move, it is not practical to have the fine type wheels 87b move in step therewith. In fact, in the embodiment herein described, it would be substantially impossible to force the fine type wheels 87b to follow the fine pointer 62. In order to overcome this difficulty without loss of speed, the operative interconnection between said groups of wheels 87a and 87b with the control motor 84 and the pointers 61 and 62, is constituted by separate self-synchronous transmitter and receiver systems. Such systems are generally referred to as synchro systems and each is provided with a transmitter and a receiver. A coarse synchro system is indicated generally at 88 and a fine synchro system is indicated generally at 89. The former system is provided with a transmitter 90 and a receiver 91. The latter system is provided with a transmitter 92 and a receiver 93. The transmitter 90 is constituted by a rotor 90a and a stator 90b, the latter being electrically connected in a well known manner to a stator 91a of the receiver 91, which stator is electrically associated with a rotor 91b. The transmitter 92 and receiver 93 of the fine synchro system are similarly connected and have analogously designated rotors and stators.

The servomotor 84, for example, by suitable mechanical means to be described in detail in connection with Fig. 7, is operatively connected to the transmitters 90 and 92. The rotors 90a and 92a are rotated at speeds which are proportional to the speeds of pointers 61 and 62, respectively.

The coarse synchro receiver 91 is operatively connected with the coarse type wheels 87a by means of a coarse servomotor 94 having a control coil 94a, an exciting coil 94b and a rotor 94c. The control coil 94a is electrically connected to the rotor 91b through the intermediary of a suitable amplifier 95 and the rotor 94c is mechanically interconnected to the rotor 91b of said re-

ceiver for driving same. When the rotor 91b gets out of step with the rotor 90a, a voltage will be generated which is amplified by the amplifier 95 and which will actuate the servomotor 94. The latter by means of its operative connection with the rotor 91b, will move such rotor into step with transmitter rotor 90a. In view of the relatively slow movement of transmitter rotor 90a, it is possible for the repeater system, including rotor 91c of the servomotor 94, to follow or track the rotor 90a throughout its range of movement.

The fine or fast receiver 93 is similarly operatively associated with the fast or fine type wheels 87b through the intermediary of a servomotor 96 having a control field coil 96a, an exciting coil 96b and a rotor 96c. The control coil 96a is connected to the coil of the receiver rotor 93b by suitable electrical means including an amplifier 97 which is analogous to amplifier 95.

The transmitter rotors 90a, 92a are in geared connection so that when the slow rotor makes one revolution, the fast one makes fifty revolutions, these revolutions corresponding to a traverse of the indicator pointers 61, 62 from zero to 50,000 lbs. It has been determined that, in a weighing device of this character, the above-mentioned time limit of three seconds is substantially the maximum that should be required for the visual indicator and its servomotor, together with the type wheels 87, to reach their maximum indications from zero to 50,000 lbs. Of course, the time required will be proportionally less for lighter loads. In accordance with the gear ratios existing in the present apparatus, which will be described below, if the fine receiver 93 were to follow the fine transmitter 92 exactly, it would be necessary for the receiver 93 to make fifty revolutions in three seconds (1,000 R. P. M.). The type wheels 87b would have to make five hundred revolutions in three seconds (10,000 R. P. M.) and the servomotor 96 would be required to make 4,166 revolutions in three seconds (83,333 R. P. M.). Such angular velocities are impossible in this type of mechanism. However, by separating the coarse and fine synchro systems into units which are independent of each other mechanically, with the exception of the geared interconnection between the transmitter rotors 90a, 92a, it is not necessary for the fine or fast system to follow the indicator 62 or the rotor 92a exactly. As the rotor 93b of the fine receiver 93 attempts to follow the indicator 62 or the rotor 92a, it cannot do so and consequently oscillates back and forth while the fast pointer 62 is traversing the dial. When such fast pointer slows down, as it does when it approaches the proper weight indication, the fast or fine receiver "pulls into step," that is, the fine rotor 93b moves into synchronism with the rotor 92a of the transmitter whereby both the fine pointer 62 and the type wheels 87b arrive at the same weight substantially simultaneously. Such pulling into step, in the embodiment herein described, requires not more than one-half revolution of one of the type wheels 87b and five revolutions of the other of such wheels. The slow or coarse system, operating at one-fiftieth of the speed of the fast system, is able to track or follow exactly with the slow pointer 61.

When the type wheels 87 have been moved as above set forth by the servomotors 94 and 96 in response to a load upon the platform 50, such wheels are aligned for printing in a straight line by a so-called sequential indexing device to be de-

scribed hereinafter, the above-mentioned print switch 82 is momentarily pressed, whereupon the printing device is actuated, as will be described later, and the weight of the draft is printed upon the scale ticket 63, together with the other desired information.

One manner of interconnecting the strain gauge means of each cell 51 is shown in Fig. 3 and consists of a bridge arrangement of resistors somewhat analogous to a Wheatstone bridge wherein two opposite arms, consisting of the strain gauge means, as at 51a, are subject to change due to loading and the other two arms 51b are fixed resistances having associated therewith suitable temperature sensitive means which compensate for so-called "zero unbalances" due to temperature variations of the cell.

Each of the cells 51 is preferably referred to as a weighing cell and the above arrangement of 20 the resistors thereof is referred to as a cell bridge. It is, of course, possible to arrange the electrical resistance type strain gauge means in other suitable circuits. The invention is not limited to such a cell bridge. In order to compensate for 25 the "zero unbalances" due to temperature variations of the cell, there may be connected in series with each cell bridge and its voltage source a temperature sensitive resistance with a linear characteristic which adjust the voltage of such 30 bridge to compensate for the linear change in the weight-voltage ratio of the output thereof, which change may occur with temperature change. The present apparatus is accurate within 5 lbs. over the range of 50,000 lbs., an accuracy of one 35 one-hundredth of one per cent. Consequently the compensation for temperature variations in the cell must be accurate and stable.

Such temperature sensitive resistances are shown, for example, as at 51c.

40 The apparatus is connected to a suitable source of electric energy (not shown), the power lines of which are indicated in Figs. 3 and 4 at L₁ and L₂. This source of energy is connected to the amplifiers, modulators, demodulators, and so forth, as shown in Fig. 3, through the above-mentioned on-off switch 78 and through a so-called 45 "power supply element" 98 which provides a high plate supply voltage electronically stabilized, and a stabilized 60 cycle tube heater voltage. 50 The power line L₁ is directly connected to the power supply element 98 through a lead 99. A second lead 100 is connectable to the other power line L₂ via said switch 78 and an intermediate lead 101.

55 The oscillator-amplifier schematically shown at 86 in Fig. 3 is shown in greater detail in Figs. 4 and 6. With particular reference to Fig. 4, the power supply element 98 is electrically connected to an oscillator 102, the purpose of which 60 is to provide a voltage source for the weighing cells 51. The portions of the apparatus shown in Figs. 4 and 6 will now be described, certain of such portions also being shown in Fig. 3.

The oscillator 102 is preferably a conventional, 65 feedback, resistance-capacity type with a degenerated stabilized buffer stage and provides a source of carrier voltage of constant amplitude and constant frequency to the cells 51 and to the slide wire 85, the frequency being about 375 cycles as above mentioned.

70 It is desirable for the voltage input to the weighing cells 51 to alternate with a frequency of approximately 375 cycles. The latter is chosen as a compromise and is as low as possible, taking 75 into account the 60 cycle interference of the

power line. Such frequency is also chosen in order to facilitate the elimination of the effects of random capacity variations which occur with time and with the displacement of the connecting cables 52. The control or servomotor 84 is of a 60 cycle, two phase type and it is desirable to use a carrier voltage frequency for the weighing cell circuit which is considerably removed from the servomotor frequency. The 375 cycle input has been found to be adequate in view of the above-mentioned compromise. The output signal of the oscillator 102 thus is of 375 cycles, preferably of five volts.

A conjugate arm of each of the bridges within the cells 51 is connected to the output terminals of the oscillator by leads 103, 104, as shown in Fig. 4. If desired, as shown in Fig. 3, there may be an individual set of leads 103, 104 for each of the cells 51. The opposite conjugate arm of each of the weighing cells is connected to a first voltage amplifier 105 by means of main leads 106 and 107, said opposite conjugate arm of each of the cells being connected to said main leads by subleads 106a and 107a. In each of the former leads is a resistance 108.

The weight on the multiple cells 51 is totalized electrically by current addition, the leads 106 and 107, together with said subsidiary leads and the resistances therein, comprising a totalizing circuit.

In order to adjust the scale zero indication, for example, upon dial 58, to zero for tare, an electrical zero adjusting network is provided, indicated generally at 109, which consists of a potentiometer 110. The latter is electrically connected to the oscillator 102 by means of leads 111 and 112, which are connected across the variable resistance of such potentiometer. Thus the voltage source of the potentiometer 110 is the same as that for the cells 51 and is preferably of the same extent, namely, five volts. This zero adjusting network is connected in series with the output of the above-mentioned totalizing circuit as shown in Figs. 3 and 4. A fixed resistance 113 is in lead 107 and the variable resistance of the potentiometer is connected across resistance 113 by means of leads 114 and 115. The output of this potentiometer 110 is adjustable at high level and is attenuated to cell signal level by such resistance 113, preferably of low value, which is in series with the cell circuit, and by a relatively large resistance 116 in series with the potentiometer arm. The above zero adjusting network is separate from means to be later described for adjusting scale zero for tare in response to synchro transmitter 92.

In series with the last described circuit is a so-called balancing network employing the above-described slide wire resistance 85 which is the main element of the null system above mentioned.

The output voltage of the weighing cells is designated e_s and can be represented as $e_s = f(W_t)$, as shown in Fig. 4. Against the voltage e_s there is balanced a counter-E. M. F. by means of said balancing network which comprises said slide wire element 85 under the influence of motor 84. Element 85 consists of a resistance wire 85a which, for example, is fixed relative to a movable contact or slide wire brush 85b in a manner to be described in greater detail below with respect to Fig. 7. Brush 85b is urged by light spring pressure against wire 85a. In order to obtain high accuracy and high resolution of the apparatus, the slide wire preferably should

10

be quite long and in the embodiment shown it is approximately sixty inches in length. For a typical scale of 50,000 lbs. capacity this provides a weight-length resolution of approximately 1 lb. per one thousandth inch of wire. It has been found desirable to wind the slide wire 85 upon a fixed drum 85c (Fig. 7) in the form of a helix and to move the slide wire brush 85b around such helix by means of the servomotor 84.

The slide wire 85a at the opposite extremities thereof is connected to the oscillator 102 by means of leads 117 and 118.

The voltage of the balancing network, of course, is varied by motion of the slide wire brush 85b in response to the servomotor 84 whereby input voltage to the amplifier 105 can be restored to null. Motor 84 is initially energized by the amplified signal from the weighing cells which is acted upon by electrical elements to be described below.

In order that the resistance of the wiring of the balancing circuit and its variation therein may be made substantially negligible, a moderately high resistance circuit is employed comprising the balancing network, there being, for example, a 1,000 ohm resistance 119 in series with the slide wire 85a, the latter being, for example, of 5 ohms' resistance. By a choice of the resistance of this balancing network, it is possible to attain accurate adjustment of slide wire calibrations with moderately large and un-critical adjustments of such series resistance 119, together with adjustment of a variable shunt resistance 120 which is connected across the slide wire 85a.

The voltage-weight relationship of the multiple cells or of a single cell is a non-linear one, the line graphically depicting such ratio dropping off with increased weight. The calibration of the dial 58 is linear and consequently the output voltage of the slide wire must also be non-linear to compensate for the above-mentioned non-linear voltage-weight ratio. In order to create a non-linear output of the slide wire, a so-called warp resistance 121 is connected between the slide wire brush 85b and the low or zero end of the slide wire, as at 85c. The warp resistance 121 accomplishes this result since the shunting effect of such resistance is greater at the high end of the slide wire, thereby dropping the voltage on the slide wire brush at the high end of the slide wire.

In order to avoid change in calibrations of the instrument over a range of ambient temperature or as the instrument heats, the resistance load on the slide wire oscillator winding is balanced against the cell load of the slide wire winding. Thus, as terminal voltage of the cells varies with the heating of the oscillator winding, the terminal voltage on the slide wire per se varies proportionately, thereby maintaining balance. A convenient means for adjusting the calibration of the instrument comprises the adjustable resistance 120 which is provided as the slide wire shunt resistance mentioned above.

In a weighing apparatus of this type wherein the maximum weight indication is 50,000 lbs., it has been found desirable for the control voltage directed to the servomotor 84 to be approximately 2 volts per pound of unbalance in order to have a resolution of about one-half pound. This control voltage for the servomotor should be stable, noise-free and preferably of 60 cycles, that is, the same frequency as the power frequency. Such a control voltage will provide adequate speed and accuracy of indication of the weight.

75

The strain gauges employed produce a full scale load voltage of approximately 0.1 microvolt per pound at, for example, the carrier frequency of 375 cycles. Thus there should be a stable, noise-free voltage amplification of approximately 20,000,000 or 146 decibels. In order for the amplification apparatus to be practical, the amplification is broken down into two stages, that is, the voltage gain is divided between two sections: the first or so-called "carrier amplifier" which provides a net voltage gain of about 20,000 or 86 decibels, and the second section or "servo amplifier" which provides a voltage gain at 60 cycles of 1,000 or 60 decibels.

As above mentioned, the total voltage of the weighing cells is expressed as $e_s = f_1 W_t$ and is also referred to as the cell unbalance voltage. The voltage supplied by the balancing network, that is, the counter E. M. F., is designated as $e_b = f_1 W_{to}$. In the above, W_t designates the applied total weight and W_{to} designates the indicated weight, that is, the weight indicated by the control servomotor 84. The voltage of the circuit at 106b (Fig. 4) is designated as e_i or input voltage, that is, the voltage input to the carrier voltage amplifier. It is also referred to as the difference voltage. The voltage e_i , of course, is the difference between the cell voltage and the balancing voltage and is expressed as follows: $e_i = f_1 (W_t - W_{to})$. The input voltage e_i is of the carrier frequency, namely, 375 cycles and is directed, as above described, to the carrier voltage amplifier 105 (Figs. 4 and 6).

The carrier amplifier 105 is a conventional type of amplifier providing approximately 86 decibels of voltage gain. It, for example, consists of four triode stages, the first two at high gain and the last two at moderate gain. A large degree of degenerative feedback is used around the first two stages and the last two stages separately, thus stabilizing the over-all gain and phasing with respect to tube variations which may occur with use and with replacement.

In the weighing of so-called "live loads," that is, loads which are not considered dead weight, for example, moving or milling cattle, it is considered highly desirable to arrive at a weight balance quickly, that is, to arrive at a weight indication quickly but when balance has been reached, to reject from the weight indication any indications which are attributable to the movement of the load caused, for example, by the stamping of the feet of the livestock or by milling. Such undesired indications which are attributable to the movement of the load are referred to as "acceleration indications" and such moving loads are referred to as "acceleration loads." Thus it is desired for the apparatus to have a high speed of response to a dead weight and to have a slow speed of response to the so-called acceleration loads which, of course, are random in nature and are also referred to as "random accelerations" or "random acceleration loads." The apparatus should be so designed that while it is coming to balance with a load upon the platform 50, the speed of response will be high but when approximate balance is attained, the random acceleration loads then must be rejected and the speed of response of the apparatus may then be reduced by suitable dampening means to be described hereinafter. It is possible to reduce the sensitivity or response of the indicator to such random accelerations by increasing the electrical dampening of the apparatus when it nears the balance

condition and also by electrical integration or averaging.

The output of the carrier voltage amplifier 105 which provides about 86 decibels of gain, is acted upon by suitable electronic means for eliminating the effects of the above-mentioned random accelerations and is thereafter further amplified to provide 60 decibels of voltage gain and is fed to the servomotor 84. The means for accomplishing this is described below, and in the form of the invention shown, comprise a demodulator 122 to which is fed the 375 cycle amplified difference voltage signal, that is, the amplified voltage e_i . The demodulator 122 converts the output signal of the carrier amplifier 105 into a phase sensitive direct current. A plus or minus D. C. voltage is thus produced by the demodulator dependent upon the phase of the input signal. The D. C. signal voltage emanating from said demodulator is thereafter filtered in a low pass filter 123 to remove demodulation harmonics and any undesirable 60 cycle noise which might have been picked up in the carrier amplifier 105.

The output of the low pass filter 123 is fed to an integration and/or differentiation circuit indicated schematically at 124. The latter element is for the purpose of filtering out undesirable frequencies which are due to the above-mentioned random acceleration loads and also for dampening the signal in order to prevent an overshoot by the indicating pointers of their accurate weight indications.

The phase sensitive demodulator 122 converts its input to a D. C. phase sensitive voltage, the amplitude of which, if there are no random acceleration loads present, will not be modulated. However, if such acceleration loads exist, there will be a random modulation of such amplitude and thus a random frequency of the superimposed envelope, that is, a random modulation of the carrier frequency. The input to the demodulator 122 is shown in Fig. 5 illustrating unmodulated and modulated carrier voltage, the latter being responsive to random accelerations; such voltage which is subject to random accelerations is indicated at e_a .

Regarding the phase sensitive aspect of the demodulator, this characteristic is necessary in order to control the direction of rotation of the servomotor 84 which, of course, depends upon the polarity of the direct current output of the demodulator 122. When the balancing voltage e_b is, for example, less than the cell voltage e_s , then there will be a positive polarity of the phase sensitive output of the demodulator 122 and vice versa.

The integration and/or differentiation element 124 always provides some degree of elimination of the effects of random accelerations. However, as above mentioned, it is desirable for the apparatus to have a high sensitivity to a dead weight and a low sensitivity to the random accelerations. In order to achieve the low sensitivity or low response to the random accelerations, the extent of integration and/or differentiation can be increased by manually or automatically controlled means. For example, when the scale device approaches the balance condition, suitable automatic means can be actuated for reducing in a greater degree than theretofore in effect, the sensitivity of the device to such random accelerations. Of course, manually controlled means can also be employed. In the form of the invention shown, the means for reducing such sensitivity of the apparatus is controlled manually by the above-described speed switch 80 which is desig-

nated the "Fast-Slow" switch. When this switch is closed, the apparatus is at so-called slow response or reduced sensitivity to random accelerations. When the switch is opened, the sensitivity is relatively higher and the apparatus responds in a rapid manner to the loads upon the platform 50.

It was explained above that it is possible to reduce the sensitivity or response of the weighing apparatus to random accelerations by either: (1) increasing the electrical dampening effect or (2) by electrical integration or averaging. It has been found desirable to employ both of these methods in the present apparatus and when the apparatus is changed from "fast" to "slow," that is, to the low speed of response, the electrical dampening effect is increased and also the effectiveness of electrical integration and averaging is increased.

In the form of the invention shown, the transfer from such fast to a slow speed of response accomplishes the following: (1) removes a shunt resistance 125 from across the output terminals of a dampening generator 126 whereby the dampening effect of such generator is relatively increased. The dampening generator 126 is driven by the servomotor 84 and produces a D. C. voltage proportional to its speed and with a polarity which depends upon the direction of rotation of the servomotor. The output of the dampening generator 126 is applied to the output voltage of the demodulator 122 in such a way that it opposes the input voltage e_1 . (2) A capacitance, as at 127, is connected across the output of the demodulator 122.

The above-mentioned resistance 125 and capacitance 127 are respectively disconnected from said generator 126 and inserted across the demodulator output through the intermediary of, for example, a relay 128 which controls a switch 129 in said shunt resistance circuit, and a switch 130 in the circuit of said capacity.

The capacitance 127 is preferably connected in series with a resistance 131, the resistance and capacity comprising a so-called integration R-C element.

When the speed switch 80 is in an open position, the speed relay 128 is deenergized and switches 130 and 129 are respectively opened and closed. When the speed switch is closed, that is, moved to the slow "position," the speed relay is energized, thereby opening switch 129 and closing 130, whereby respectively the dampening effect of the generator is relatively increased and the integration and/or differentiation effect of the element 124 is relatively increased.

Regarding the integration and/or differentiation element 124, such element depending on the particular use of the apparatus, will provide more or less integration and/or differentiation and in certain uses of the apparatus it is, of course, conceivable that none will be needed. For example, if it is desired to weigh only a so-called dead weight wherein no random acceleration loads are encountered, the element 124 will not be needed.

By employing the above-described sensitivity control, it is possible for the servomotor 84 and the pointers 61 and 62 to accelerate rapidly to approximate speed in the presence of an unbalance or load and as a balanced condition is approached, such pointers and servomotor can be decelerated rapidly and can approach accurate full weight indication or balance without so-called crawl or overshoot of the mark. A high

torque gradient is desirable and is obtainable by means of this circuit at the balance condition of the apparatus and such high torque gradient is important in order to reduce to a negligible degree the so-called "lost motion" or "dead space" at the balance condition. These conditions are satisfied without an excessive maximum control voltage for the servomotor. By employing electrical integration with respect to the output of the demodulator 122, the signal is critically damped by so-called viscous speed feedback and the servomotor 84 and the indicators 61 and 62 approach the balance condition without the crawl which is normally associated with viscous damping when employed alone.

The direct current signal voltage emanating from the demodulator 122 and modified by dampening and integration, as explained above, is applied to the input of a balanced modulator 132, the output of which is a 60 cycle A. C. signal voltage of a phase determined by the polarity of the above-mentioned D. C. signal output of the demodulator 122. This 60 cycle voltage is then amplified by a push-pull stage of voltage amplification and thereafter by a push-pull stage of power amplification in a suitable voltage amplifier 133 which is also designated a "servo amplifier," and the output of the latter is coupled to the servomotor 84 through the intermediary of a suitable transformer. A control coil 84a of the servomotor 84 is electrically connected to said transformer and an exciting coil 84b for such motor is connected to the 60 cycle 115 volt power supply as indicated in Fig. 3. The servomotor 84, as explained, is operatively associated with the slide wire element 85 and controls the movement of the slide wire brush 85b through a mechanism to be described more fully hereinafter. This servomotor is of low inertia. Said exciting coil 84b is connected to the power supply through a condenser as at 84c, the latter producing a 90° phase shift between the exciting and the control voltage. The control voltage in the control coil 84a is, with respect to its phase, plus or minus 90° depending upon the direction of unbalance, and the motor 84 thus will run in a direction to restore balance and in so doing operate the pointers 61 and 62 in the manner above explained.

As above mentioned, the servomotor 84 is geared to the synchro transmitters 90 and 92 in such a manner that when the slow transmitter 90 makes one revolution, the fast transmitter 92 makes fifty revolutions. The transmitters 90 and 92, therefore, transmit electrically the positions of the high and low speed pointers and said transmitters can be used for the control remotely of a device such as the above-mentioned printer 56.

60 *Zero reset of scale 58*

As above explained, in the normal operation of a scale, for example, a livestock weighing scale, certain residual loads will occur thereupon due, for example, to the droppings which are left upon the platform by the livestock. Furthermore, so-called instrument drift may occur. Such residual load and drift make it necessary frequently to apply a tare correction, that is, to reset the indicating pointers 61 and 62, and particularly the fast pointer 62, to zero. For example, there may be 50 to 60 lbs. of such residual load upon the platform 50 which, when the platform is empty of livestock, will be accurately indicated upon the dial 58 whereupon the pointers

61 and 62 should be accurately reset to zero. In order to accomplish this with maximum accuracy and freedom of operator error (deliberate or inadvertent) provision is made for resetting the indicators 61, 62 to zero either automatically or manually. If desired, automatic actuation of the zero reset means can be effected, for example, in response to an approaching load as by a suitable switch subject to such load, or by the closing of a gate of a platform enclosure. In the embodiment shown, provision is made only for such manual actuation of the resetting means. This portion of the apparatus is termed a zero reset element and in general is constituted by means responsive to the voltage output of the fast synchro transmitter 92, which voltage is suitably amplified, for example, by the amplifier 97 and thereupon fed to suitable means, such as a servomotor, for introducing the desired correction to the indicating pointers 61 and 62, and simultaneously by an operative interconnection adjusting the rotor 92a of the synchro transmitter 92 in such a way that the voltage output thereof is reduced to zero.

A zero reset mechanism of the above nature is shown schematically in Fig. 3 and comprises a zero adjusting motor 134 which, for example, is of a two phase 60 cycle A. C. variety, having an excitation coil as at 134a which is connected to the 115 volt 60 cycle power supply, as shown in Fig. 3, and also having a control coil 134b which is electrically associatable with the output of the so-called fast or fine indicator amplifier 97 by means of a series of switches to be described more fully below. The zero motor 134 and its connections with the indicating pointers 61 and 62 and also with the fast and slow synchro transmitters is indicated in greater detail in Fig. 7. In general, said zero motor 134 introduces a zero adjusting correction to said pointers through the intermediary of a differential 135 which latter differential is jointly controlled by the servomotor 84 in a well known manner, as will be explained below in connection with Fig. 7. The output of the differential 135 is by suitable interconnections, such as a gear train, in driving association with the coarse and fine pointers 61, 62 and by similar means is in driving connection with the transmitters 90 and 92. The means for actuating the servomotor in response to a residual load, that is, in response to a voltage output of the synchro transmitter 92, are as follows: the above-described zero switch 79 when momentarily closed as by pushing with a finger, energizes a pair of relays 135 and 137 and in addition energizes a so-called thermal timer relay 138 with a relay holding contact in series with the timer control contacts. Normally upon the release of the switch 79 to its normally open position, said relays would become deenergized. However, the so-called thermal timer and its associated relay device operate to maintain said relays 136 and 137 in an energized condition for a period, for example, of five seconds. The relay 136 is operatively associated with a switch 138a which when closed in response to energization of relay 136 actuates the thermal timer relay mechanism 138. The relay 137 is operatively associated with a pair of two-way switches 139 and 140 which normally, in the deenergized condition of said relay 137, interconnect two of the output leads of the synchro transmitter and receiver 92, 93, respectively. However, upon energization of the relay 137, said switches 139 and 140 are thrown to such a position that the synchro receiver 93 is in ef-

fect by-passed and said two leads are connected to the amplifier 97 via a switch 141 which also is of the two-way type and which is interposed intermediate the rotor of the receiver 93 and its amplifier 97 in one of the interconnecting leads therebetween. The switch 141 is actuated in response to energization of the relay 136, as is shown in Fig. 3.

The control coil 134b of the zero adjusting motor 134 is connectable across the output terminals of the amplifier 97 by leads 134c and 134d through a two-way switch 142 which normally is in such a position as to interconnect the servomotor 84 with said amplifier 97. However, upon energization of relay 136, to which said switch 142 is operatively interconnected, the latter switch is thrown to a position whereby the control coil 134b is connected across the output of the amplifier 97 and the servomotor 84 is disconnected from said amplifier.

Consequently upon the momentary closing of the zero switch 79, all of the switches 139, 140, 141 and 142 are shifted substantially simultaneously to such a position that the control coil 134b is connected across the output of the amplifier 97 and thus across an amplified output of the synchro transmitter 92. The latter, of course, governs a voltage in response to the position of the fine indicator pointer 62.

The energization of the coil 134b actuates the zero adjusting motor 134 and introduces a correction to said pointers and also to the synchro transmitter 92, whereby the rotor thereof 92a is reset to its zero position. That is, when said synchro transmitter reaches a position corresponding to scale zero, its voltage becomes zero and the zero adjusting motor 134 stops. The five second interval during which time the relays 136 and 137 are maintained in an energized condition is normally sufficient time to allow the zero adjusting motor 134 to correct any usual shifting of the indicator 61, 62 due to residual load. At the end of the five second interval, the timer opens the relay 138 and thereupon the relays 136 and 137 are both deenergized, dropping the circuits back into their normal conditions whereby the printing mechanism is operatively connected thereto.

Stop switch

As above explained, a stop switch 81 is provided which is preferably of a toggle variety and can be in either a so-called "run" position or "stop" position. The function of the stop switch primarily is to arrest the indicating pointers 61, 62 and, of course, the servomotor 84 in whatever position desired. This is accomplished by controlling a stop relay 143 (Fig. 3) which in turn governs a shunt switch 144 across the control phase or control coil 84a of the servomotor 84. In the form shown, a closing of the stop switch 81 in turn closes an intermediate switch 81a which is connected in the circuit of the stop relay 143 and by closing of the latter energizes said relay and inserts the shunt 144 across said control coil 84a. Simultaneously with the arresting of the servomotor 84 by the closing of the switch 81, there is energized a red signal light 145 which, for example, can be energized by closing of a suitable switch in response to the energization of the relay 143, such switch being indicated, for example, at 146. Such red glow lamp 145 gives a visual indication of whether or not the stop relay 143 is energized and thus whether or not there has been an arresting or deenergizing of the control motor 84. Glow lamp 145 is also shown in Fig. 1

in connection with the indicator 53, as is a further glow lamp 147 which can be connected across the main 115 volt 60 cycle power supply, as shown in Fig. 3, to indicate whether or not the system is energized. The lamp 147 is energized in response to the closing of the master on-off switch 78.

An automatic stopping of the control motor 84 preferably is accomplished in response to a momentary closing of the zero switch 79. In the form shown, this is accomplished by means of a switch 148 which by-passes the intermediate switch 81a and is adapted for energizing the stop relay 143 in response to the energization of relay 136, the latter being responsive to the switch 79.

Suitable incandescent lamps, one of which is shown as at 149, can be employed for illuminating the dial 58 and can be connected across the 60 cycle 115 volt power supply, as shown in Fig. 3, and energizable in response to the closing of the on-off switch 78, there being a suitable transformer 150 for stepping down the voltage, for example, to 6 volts.

It was explained above that in column 65 of the scale ticket 63 it is desired, in connection with a stockyard scale ticket, to record the time in the form of the year, month, date, a. m. or p. m., hour and minute. A suitable device is provided for this purpose which is preferably driven by a synchronous clock motor, as at 151, which is connected across the leads 99 and 101 in such a manner that it is not under the influence of the on-off switch 78. The clock motor 151 can be operatively associated with the time indicating device, for example, through a suitable switch 152, which can be closed by suitable mechanism every minute for the energization of a clock solenoid 153 which, when energized, actuates the time indicating means, making the necessary adjustments at intervals of one minute.

The above-described relays, such as the speed relay 128, the stop relay 143 and the relays 136 and 137, are provided with a source of electric energy through a transformer 99a which is connected across the power leads 100, 101. The output of this transformer is of suitable reduced voltage for such relays and can also be employed in the amplifiers 95 and 97 by the connections shown in Fig. 3.

Printing device motor

A motor, as at 154, is employed for actuating the printing device in response to the closing of the printing switch 82. The printing motor 154 is connected across the power leads 99 and 100 by means of leads 155 and 156, as is shown schematically in Fig. 3. Interposed in the lead 155 in a position for deenergizing the printing motor 154 is a microswitch 157 which is operatively associated with the motor 154 in such a way that when the printing cycle is started, that is, when the printing motor 154 is energized by momentarily closing the switch 82, said microswitch 157 maintains the energization of the printing motor 154 sufficiently long to insure that a preselected number of revolutions is made under power to complete a so-called "printing cycle" of the printing device. That is, when the printing switch 82 is momentarily closed, the motor 154 is energized and, for example, through a cam operative interconnection, the microswitch 157 is closed for a sufficient time to enable said motor to make a preselected number of revolutions which will drive a reference shaft through, for example, one revolution to complete

such printing cycle. The microswitch 157 is in parallel with the print push button switch 82, whereby only a momentary closing of the latter switch is necessary in order to close switch 157 to energize the print motor circuit for an adequate time.

The print motor 154 provides the power for operating a plurality of mechanisms, as will appear in detail hereinafter.

- 10 The above-mentioned printing push button switch 82 is connected in parallel with the print motor microswitch 157 through the intermediary of a lead 155a which is connected across the microswitch 157. Interposed in said lead 155a are the switch 82 and also the stop switch 81. In addition to these two switches, there is also interposed in said lead a double pole switch 83a which is under the influence of a ticket indexing device to be described more fully hereinafter.
- 15 The switch 83a is connected in the print motor electrical circuit in such a way that (a) it is capable of breaking the circuit to the print push button switch 82 (Fig. 3) when the ticket holder 73 is out of position for printing, (b) it will break the circuit to the push button switch 82 after the last line, as line (3) of the scale ticket 63, has been printed, and (c) when the ticket holder 73 is in the position for printing upon any of the lines (1), (2) or (3), said switch 83a will light 20 the above-described glow lamp 83.

Servomotor operated elements (Fig. 7)

Referring now to Figs. 3, 7 and 8, with particular reference to Fig. 7, there will now be described the operative interconnection between the main control or servomotor 84, the indicating pointers 61, 62, the slide wire resistance element 85 and the zero adjusting motor 134.

- 25 The servomotor 84, as above described, drives the indicating pointers 61, 62 through the intermediary of a differential 135 having a beveled input gear 135a and a beveled output gear 135b. Said input and output gears are interconnected by a conventional spider gear 135c which is rotatable about its axis upon a shaft 135d which in turn is movable in a planetary fashion under the influence of a shaft 158 which is normally held in a locked or stationary position by means of a worm and wheel 159, 160 for a purpose to appear below. The servomotor 84 is connected to the input gear 135a through the intermediary of suitable gears which are located within a gear box as at 161 and which for purposes of clarity are not shown. The output differential gear 135b positions the pointers 61, 62 through a suitable gear train, two of the gears of which are indicated as at 162 and 162a. As above described, such indicating pointers 61, 62 are geared to rotate in said preselected speed ratio, namely, 50 to 1, that is, the fine pointer rotates fifty revolutions when the coarse pointer rotates one revolution.

30 The spider gear is designated 135c and its shaft 135d. The shaft 158 is connected to the shaft 135d, said shafts being at right angles to one another. Thus shaft 135d can shift angularly under the influence of the zero motor 134 to any required angular position.

- 35 The slide wire 85a, as above explained, is approximately 60 inches long and is wound upon a stationary drum 85c with approximately five and one-quarter turns in the form of a spaced helix. The drum 85c is held stationary by suitable means (not shown) and the slide wire brush 40

75

85b is rotated around the drum and advanced axially thereof in order to follow the helix. The means for so advancing the slide wire brush 85b comprise, in the form shown, a threaded shaft 163 which is received in a suitable threaded recess in an arm 164 which mounts the slide wire brush 85b. The slide wire brush 85b is caused to follow the helical wire 85a by a combination of (1) rotation of the threaded shaft 163, and (2) planetary motion of said shaft 163 and the arm 164 around the stationary drum 85c. The threaded shaft 163 is caused to rotate by means of a gear 165 rigidly attached thereto which engages a stationary gear 166.

The planetary motion of the threaded shaft 163 and the arm 164 can be accomplished, for example, by moving a bearing shaft 167 for said threaded shaft, in a planetary fashion about said stationary drum by means of arms 168, 169 which are secured for rotation to a shaft 170 which is coaxial with the drum 85c. Shaft 170, by suitable gearing, is drivably connected to the main or control servomotor 84.

In order to minimize the wear upon the slide wire brush 85b and to assist in maintaining a clean contact between it and the slide wire 85a, said brush is constructed with a dimension measured axially of the drum 85c, considerably in excess of that necessary to make contact with a single turn of the wire, and preferably is slightly less than the pitch of the helix formed by the wire. The pitch of the threads upon the threaded shaft 163 is such that as the arm 164 and the brush 85b are advanced axially and planarily of the drum 85c, the slide wire brush 85b or its wiper contact portion per se will be advanced axially at a rate faster than it would be if the pitch of the helical wire 85a were followed. That is, the pitch of threaded shaft 163 is sufficient to advance the brush 85b in such a manner that for one complete traverse of the slide wire 85a a different portion of the brush 85b is presented progressively to such slide wire. Thus there is a sidewise wiping action of the brush 85b with respect to the resistance wire 85a as the former moves axially across and planarily about the drum.

Zero adjusting motor 134 governs the above-described zero scale correction for tare by driving the worm 159 of the locking worm and wheel arrangement 159, 160. This is accomplished through a suitable gear train, as in a gear box 171, which drives an input shaft 172 to the worm 159.

The operative interconnection between the pointers 61 and 62 and the self-synchronous repeater systems 88, 89 are schematically indicated in Fig. 7 wherein the coarse or slow transmitter 92 is operatively interconnected to the coarse indicator 61, the line of interconnection being indicated as at 173. An analogous line of connection is indicated as at 174 between the fine indicator 62 and the fine or fast transmitter 90.

It is to be understood that it is within the purview of the present invention to omit the visual indicators 61, 62 and their associated scales.

The gearing interconnecting the pointers 61, 62, and said transmitters 90, 92 can be located within a gear box 175.

For the sake of simplicity, as above mentioned, the gear trains in the gear boxes 161, 171 and 175 are not shown. The nature of these gear trains, of course, varies with the use to which the apparatus is put. For the particular device herein

described, the gear ratios of certain of the units are as follows: When pointer 61 makes one revolution: pointer 62 makes fifty revolutions, transmitter 92 makes one revolution, the transmitter 90 makes fifty revolutions, slide wire brush 85b makes five revolutions and the control servomotor 84 makes one thousand revolutions. Regarding zero weight adjustment: When the zero adjusting motor 134 makes five thousand revolutions, shaft 172 makes one hundred fifty revolutions and shaft 159 makes three revolutions.

In order to prevent damage to the mechanism, for example, in case a load is placed on the platform 50 in excess of the capacity of the scale or if such platform should be raised off the weighing cells 51 when the mechanism is in operation, suitable means are provided for cutting off the current to the main control servomotor 84 and for promptly stopping its rotation. This is done in order to prevent the slide wire 85b from running off an end of the helical wire 85a.

Means for accomplishing this are shown generally at 176 and comprise a safety stop or limit stop, a part of which is indicated in detail in Fig. 8. The safety stop comprises generally a bifurcated or fork member 177 which is angularly shiftable upon a pivot pin 178 within relatively small limits of angular motion. The fork member 177 is provided with legs 177a and 177b. The legs 177a, 177b are normally centered between limit switches 179 and 180, the former and latter legs being respectively adjacent to the switches 179 and 180. A suitable spring can be employed for holding the fork member 177 in such centered position. The switches 179 and 180 control the motor 84 electrically and effect its reversal.

Attached to the fork member 177 is a resilient arm 177c which is positioned for operative association with an arm 181 having a crank pin 181a secured to the outer extremity thereof, said arm 181 being rotatable upon a shaft 182 in a preselected speed ratio with the slide wire brush 85b. For example, shaft 182 is geared by suitable means within the box 161 to make one revolution when the brush 85b makes 5.2 revolutions around the drum 85c.

In addition to controlling the motor 84 by electrical switches 179 and 180 which reverse the motor, a mechanical stop for such motor is provided preferably of a cushioned variety whereby angular movement of the motor is yieldingly arrested immediately upon the actuation of either one of the switches 179, 180. This is accomplished by the following means: a shaft 183, by means of suitable gearing within the box 161, is caused to rotate at the same speed as the servo motor 84. Secured to the shaft 183 for rotation therewith is a spool-shaped member 184 which is located between the legs 177a, 177b of the fork member 177. A coil spring 185 is coiled loosely around a core 184a of the spool 184 and the extremities of such spring are bent in the form of open hooks which extend in opposite directions as at 185a and 185b of Fig. 8. Between the end flanges of the spool 184 and outside of the periphery of the coil spring 185, but inside of the hooked extremities 184a and 184b, a bar 186 is secured in order to permit the coil spring 185 to wind tightly about the core 184a of the spool 184, as will be explained below.

For cooperation with the open hook ends 185a and 185b, respectively, there are provided upon fork 177 inwardly extending spurs 187 and 188. These spurs are respectively mounted upon the

fork legs 177a and 177b. Normally the spool 184 is centered between the legs 177a and 177b and the hook ends 185a and 185b cannot engage said spurs. Thus when shaft 183 is rotating clockwise, as shown by the arrow 183a, the spool 184 and the spring 185 are free to rotate with it until the crank pin 181a contacts the spring 177c whereupon it will thrust the fork leg 177a, for example, upward, thereby operating limit switch 179 and at the same time moving the spur 188 upwardly until it is within the range of movement of the open hook 185b, thereby causing the spring 185 to be wound up upon the spool by virtue of the bar 186 engaging the opposite hook end 185a. The angular motion of shaft 183 and servomotor 84 thus can be yieldingly arrested or brought to a cushioned stop. If the shaft 183 is rotated in the opposite direction, the fork leg 177b will be thrust downwardly to actuate the limit switch 180, whereupon the spur 187 will be engaged by the hook end 185a and the shaft 183 and motor 84 brought to a cushioned stop in an opposite direction.

Arm 181 and pin 181a are adjusted to engage resilient arm 177c when brush 85b is near each extremity of wire 85a.

Printing device

The general construction of the printing device 56 is shown in Figs. 9 and 10. For purposes of convenience, the printing device or printer 56 is made in two sections which are in hinged association and comprise an upper section 189 and a lower section 190. These two sections are mounted so that the upper section 189 can be angularly shifted upwardly to the position as shown in Fig. 10 for adjustment and servicing. This is accomplished, for example, by means of a hinge rod 191 which is supported on the lower section 190 in suitable brackets 192. The brackets 192 are rigidly attached to a base plate 190a of the lower section 190. The hinge rod 191 thus supported extends into suitable recesses of side plates 189a of the upper section 189.

In Fig. 9 there is shown a roll of carbon ribbon, as at 193, which is mounted upon a suitable supporting bracket 194, and which is directed over a suitable platform 195 beneath which hammers and platens (to be described below) are mounted for striking upwardly, as viewed in Fig. 9, beneath the scale ticket 63 through a slot 195a in said platform, whereby the scale ticket 63 is urged against embossed type wheels for the printing of the desired data on the ticket in a manner to be explained more fully hereinafter.

For purposes of clarity, the carbon ribbon and its supporting platform and related elements are shown in Fig. 9 with certain other elements of the printing device omitted, such other elements being shown in Fig. 10 with the carbon ribbon 193 and the platform 195 omitted.

The roll of the carbon ribbon, as at 193, is mounted in such a way that the web thereof 193a is initially directed toward the front of the device, as viewed in Fig. 9, and the direction of movement of such web is changed by 90° to move across the platform 195 by means of an angularly disposed guide bar 196.

The web 193a of the carbon ribbon is pulled across the platform 195a in preselected increments by means of a carbon ribbon indexing unit 197 which will be described in detail below in connection with Figs. 28 and 29.

When said upper and lower sections are in their normal operating positions, as in Fig. 1,

they are locked together by means of hooked levers 198 which are adapted for engaging suitably positioned recesses in lock plates 199 fixed to lower section 190 whereby the two sections can be firmly held together. The hooked levers 198 are preferably operable by means of suitable keys 198a which can actuate conventional locks for shifting lever 198 into and out of engagement with the recesses in plates 199.

In order to facilitate servicing and replacement of parts, there are located both in the upper and lower sections 189 and 190 of the printer, unit sub-assemblies which can be easily removed and replaced as units and which will be described individually below.

Referring to Fig. 10, these units in the upper section 189 are as follows:

(1) A time unit 200 consisting of a driving mechanism and a plurality of wheels having embossed upon the peripheries thereof suitable indicia for the printing of the year, month, day, a. m. or p. m., hour and minute. The above-described synchronous electric motor 151 (Fig. 3) is preferably positioned, as in Fig. 10, for driving the time unit 200. The type wheels of the time unit 200 are positioned for printing in column 65 of the scale ticket 63 (Fig. 2).

(2) A scale number unit, as at 201, is preferably secured to the time unit in position for printing in column 66 of the scale ticket 63. The scale number unit comprises, for example, a slug having embossed thereupon the serial number of the particular scale device.

(3) Adjacent the scale number unit 201 there is located a draft number unit 202 comprising a plurality of type wheels which are adjustable for printing in column 67 the number of the group of livestock which is being weighed. The type wheels of this unit are shifted one numeral, by any suitable means, each time the printing device is operated.

(4) Adjacent the draft number unit 202 there are located a plurality of type wheels, as at 203, which are adapted for printing in columns 68, 69 and 70 (Fig. 2) which, in the form shown, provide a space for indication of (a) species of livestock, (b) number of individuals, and (c) the commission agent's symbol. These type wheels are positionable by means of levers 203a and associated sector gears, to which levers there are secured the manually adjustable knobs 68a, 69a, 70a, 70b (Fig. 1).

(5) A weight unit 204 is positioned adjacent the type wheels 203 and comprises the weight type wheels 87 and their adjacent control mechanism, such as a type wheel aligning mechanism 205 (Fig. 16) to be described below. Such wheels are shown in greater detail in Fig. 12. These type wheels are automatically adjusted in position to print whatever weight is placed upon the platform 50 with the aid of the weight responsive means and the synchro systems 88, 89 described above in connection with Fig. 3.

(6) Secured to the weight unit 204 is a member 206 having a suitable slot therein for the insertion of a removable facsimile signature slug 207, such slug being positioned for printing in the space 72 of the scale ticket 63 whereby the time is saved which normally is used for the weight master to sign his name.

The above-mentioned units are preferably secured in place within the upper section 189 by means of the hinge rod 191 and also by means of a rod 208 (Fig. 11), the latter rod being located behind said units, as viewed in Fig. 10.

To illustrate an example of this means for mounting the units, reference is made to Fig. 11 wherein the weight unit 204 is seen in cross-section as being hingedly secured to the rod 191 by means of a journal 204a at the lower portion thereof, the upper portion of the unit being adjustably secured to the rod 208 by means of a pin 209 which is pivotally associated at 210 with the weight unit 204 and which extends through a bore 208a in the rod 208 and is there adjustably positioned by means of nuts 211 and 212 which engage a threaded extremity of pin 209 on opposite sides of the rod 208.

Referring again to Fig. 10, in the lower section 180 of the printer 56 there are located the following principal units, all of which are secured to the base plate 190a:

(1) Amplifiers 95 and 97 which are employed with the synchro systems 88 and 89 (Fig. 3).

(2) The print motor 154, which provides the power for operating:

(a) Platens or hammers 213 which are caused to strike upwardly, as viewed in Fig. 10, and urge the scale ticket against the carbon ribbon web 193a and the type wheels. Such hammers will be described below in greater detail in connection with Figs. 26 and 27.

(b) Mechanism for controlling the position of the scale ticket 63 as held within the ticket clamp 73. Such mechanism is designated a ticket indexing unit and is shown at 214 (Fig. 10) and will be described hereinafter in connection with Figs. 23-25.

(c) The mechanism 205 for aligning the weight type wheels 87 whereby the embossed numeral upon such wheels are adjusted to a position for printing on a straight line. Such aligning mechanism is designated as a type wheel aligner and will be described below in connection with Figs. 15 and 16.

(d) The carbon ribbon indexing unit 197.

Other elements are actuated by the print motor 154, as will appear hereinafter.

(3) A print motor gear reduction unit 215 which is driven by motor 154 and operatively associated with a main power shaft 216 by means of a solenoid operated clutch 217, a solenoid 218 of which is electrically associated with the circuit of the print motor, as shown in Fig. 3. The solenoid 218 is energized in response to the energization of motor 154 and closes the clutch 217, whereupon the main power shaft 216 is driven, for example, through one revolution, whereupon the motor 154 and solenoid 218 are deenergized, the clutch 217 is opened and the motor is permitted to coast. This is accomplished by means and for a purpose to be explained hereafter.

(4) The platen or hammer units 213 above mentioned, which are mounted for striking against the scale ticket 63 and the type wheels for printing in a manner reversed from the ordinary typewriter action.

(5) The ticket indexing unit 214.

(6) The carbon ribbon indexing unit 197.

The motor microswitch 157 is under the influence of a cam 157a (Fig. 10) which is rigidly secured to the main power shaft 216 and is adapted for being shifted through 360° each time the print motor 154 is energized in response to the closing of switch 82. When the latter switch is closed momentarily, the print motor 154 actuates cam 157a and closes switch 157 until one revolution of said shaft 216 and cam 157a is

completed, whereupon switch 157 is opened by said cam.

Hammer actuating mechanism

5 Referring again to Fig. 11, and also to Figs. 26, 27 there will now be described the mechanism for actuating the hammers or platens 213, with particular reference to hammers 213a which are positioned for striking the ticket beneath the weight type wheels 87.

The weight unit 204 is secured by means above described within the upper section 189. The latter section, as shown in Fig. 11, is in its normal operating position with respect to the lower section 190 whereby the weight type wheels are positioned over the slot 195a in the platform 195. The latter platform supports the scale ticket 63 and also the carbon ribbon web 193a in the relative positions shown, that is, the carbon ribbon is interposed between type wheels 87 and the scale ticket 63. The platform 195 is preferably supported upon the base plate 190a by means of supporting columns 195b. The hammers 213a are pivotally mounted at 219 between a pair of end plates 220, one of which is omitted in Fig. 11 for purposes of clarity. The heads of the hammers 213a are preferably faced with a strip of resilient material, such as rubber, as at 221, which may be normally positioned flush with the upper surface of the platform 195, as shown in Fig. 11. This may be accomplished by means of a generally V-shaped lever 222 having secured thereto a cross rod or pin 223 upon which said hammer rests, said lever 222 being preferably pivotally mounted at 219 and resiliently held against a limit stop 224 by means of a spring 225.

The hammers 213a are preferably operated by energy stored in the spring 225 by means of a cam 226 which is rigidly secured to said main power shaft 216 which is rotatable by the print motor 154. The cam 226 is positioned for engaging a leg 222a of the lever 222 and the profile of such cam is such that the leg 222a when engaged by the cam is thrust downwardly, as viewed in Fig. 11, whereby the spring 225 is extended and simultaneously the hammers 213a are lowered for striking by virtue of the lowering of the cross rod 223 upon which said hammers rest. When the shaft 216 is rotated sufficiently so as to extend the spring 225, a peak 226a of the cam is reached whereupon the leg 222a is suddenly disengaged from said cam and the lever 222 snaps back to its original position against stop 224 under the influence of spring 225, thereby throwing the hammers 213a upwardly. The resilient faces 221 strike through the slot 195a and urge the scale ticket 63 against carbon web 193a and the embossed type wheels 87 causing the carbon ribbon to print the impression of the type on said scale ticket.

A plurality of scale ticket carbon copies can be legibly printed by this mechanism providing, of course, suitable carbon paper is interposed between the scale tickets.

Weight unit

The above-mentioned weight unit 204, which is located in the upper section 189, will now be described, including the mechanism for driving the type wheels and aligning same to print in a straight line. Reference is made particularly to Figs. 12-22, inclusive.

The weight unit in the form of the invention shown includes means as at 205 (Fig. 16) for positioning the type wheels 87 (Fig. 12) so that

when properly aligned thereby, they will print in a straight line. The following description, for purposes of illustration only, applies to a printing unit where it is desired to print any value as of weight between the above-described limits, that is, between 0 and 50,000 lbs., the accuracy being to the nearest 5 lbs. although, of course, the apparatus herein described is of considerably higher accuracy. Thus in the example to be described, the printer should be able to print an indication of the weight as follows: 00000; 00005; 00010; etc. to 49990, 49995 and 50000. The servomotor 84 is capable of moving to its final position and also moving pointers 61, 62 to their final positions from 0 to 50,000 within three seconds, such small time limit being desirable in order to expedite the weighing process. The type wheels 87 should be so adjusted and aligned that they are prepared to print the scale ticket when the indicating pointers 61, 62 reach their final position. Of course, proportionately smaller time is required for the indicating pointers to reach indications lower than the maximum.

The type wheels, as shown in Fig. 3, are employed for this purpose and are illustrated in more detail in Fig. 12. These type wheels are divided into four elements, two of which, as at 87b, are operatively associated with the servomotor 96 for fine indications of the weight, and the other two elements, as at 87a, are associated with the servomotor 94 for coarse indications. Such four elements are coaxially mounted and rotatable upon a fixed shaft 227 and comprise a first element 228 which is at the righthand of Fig. 12 and which consists of two separate type wheels 228a, 228b which are rigidly secured to a drive gear 279 and a twenty point star wheel 230. The shaft 227 provides merely a support for the type wheel 87 and in the form shown is not a driven shaft. Such type wheels are driven as explained in connection with Figs. 13 and 14. The two type wheels 228a and 228b are rigidly secured to said gear and star wheel, for example, by rivets and such gear and wheel are preferably interposed between these type wheels. The numerals are embossed equally spaced upon the peripheries of the wheels 228a and 228b, whereby jointly they can print 00; 05; 10; 15; 20; up to 85; 90 and 95, as indicated in Fig. 12. A second type wheel element is indicated generally at 231 and consists of a type wheel 232 having rigidly secured thereto a drive gear 233, a ten point star wheel 234 and a cam 235, the latter being for a purpose to appear more fully hereinafter. The type wheel 232 has embossed upon the periphery thereof at equally spaced intervals numerals 0 to 9.

A third type wheel element is indicated generally at 236 and consists of a type wheel 237, a star wheel 238 and a drive gear 239, all of which are also rigidly secured together as by rivets. The type wheel 237 is embossed with numerals similar to wheel 232.

A last type wheel element is indicated at 240 and consists of parts analogous to element 236, namely, a type wheel 241, a drive gear 242 and a ten point star wheel 243, all of which are rigidly secured together. The type wheel 241 has embossed thereupon numerals 0 to 9.

The above-described star wheels are employed as part of a mechanism for indexing or aligning the numerals upon the type wheels for printing in a straight line. Such mechanism will be described hereinafter in connection with Fig. 16.

Type wheel drive and gearing (weight unit) —

Reference is now made to Figs. 12 and 13 which indicate in detail the operative interconnection between the synchro transmitters 91 and 93 with the groups of type wheels 87a and 87b, respectively. Shown in Fig. 13 is the mechanism for operating type wheel elements 228 and 231. This is a portion of the so-called "fast" or "fine" indicating system.

In Fig. 14 there is shown an analogous operative interconnection between the coarse synchro transmitter 91 and the type wheel elements 236 and 240 which are portions of the so-called "slow" or coarse indicating system. The mechanisms shown in Figs. 13 and 14 are entirely separate 10 electrically and mechanically with the exception, of course, that they have a common source of electric energy and respond to a common force, namely, the weight upon the platform 50. Both the fast and slow operative interconnections in 15 Figs. 13 and 14 are basically identical with the exception of certain gear ratios.

Referring to Fig. 13, the power for driving the type wheel elements 228 and 231 is provided by the above-described reversible servomotor 96 20 through the gear train shown. The fine or fast synchro receiver 93 is operatively connected to the servomotor 96 by a connection into said gear train and is driven thereby. The type wheel elements 231 and 228 are driven in the ratio of 1 to 20, respectively. Such type wheel elements print the last three digits of the weight.

The fast synchro receiver 93 is electrically connected to the fast transmitter 92, as schematically indicated in Fig. 3, in such a way that when the 25 receiver 93 is out of step with the transmitter 92, a voltage occurs which is amplified by the amplifier 97 and applied to the servomotor 96 whereby the latter is rotated either clockwise or counterclockwise to bring said transmitter and receiver into step. Thus the type wheel elements 228 and 231 are caused to register the same weight as the fine pointer 62.

The number of teeth upon each of the gears, as shown in Figs. 13 and 14, is indicated by a 30 numeral thereon followed by the letter "T" and comprises one example of a convenient set of gear ratios for this purpose.

The so-called slow or coarse indicating mechanism shown in Fig. 14 operates in the same manner as that shown in Fig. 13. That is, the slow or servomotor 94 drives the slow or coarse synchro receiver 91 through a suitable gear train and also drives the type wheel elements 236 and 240. The synchro receiver 91 is electrically connected to the synchro transmitter 90, as shown in Fig. 3. When the synchro receiver 91 is not in step with the transmitter 90, a voltage occurs which is amplified by the amplifier 95, as above explained, and applied to the coarse motor 94 to rotate same either clockwise or counterclockwise to bring the receiver 91 into step with its transmitter. In this manner the type wheel elements 236 and 240 are made to follow the slow or coarse pointer 61.

By having the two synchro systems 88 and 89 separate from each other mechanically, with the exception that the rotors of the transmitters 90, 92 are geared together to rotate in a preselected speed ratio, it is not necessary for the fine receiver 93 to follow the fine indicator 62 or the rotor 92a exactly while coming up to weight. That is, when a substantial load is placed upon the platform 50, the servo motor 84 and the indicating pointers 61 and 62 will move over their 70 respective scales in a very short increment of 75

time (less than three seconds) and reach the balance point. The fine transmitter rotor 92a will be rotated at the same speed as the fine indicator 62. However, the fine receiver rotor 93b does not follow the fine rotor 92a. As said rotor 93b attempts to follow the rotor of its transmitter, it cannot do so and oscillates back and forth while the fine indicator pointer is moving over its scale. Then when said fine pointer slows down sufficiently when it nears the balance point, the rotor 93b will pull into step with its transmitter rotor 92a whereby both the fine pointer 62 and the fine indicating type wheel elements 228 and 231 arrive at the same indication substantially simultaneously. As above described, the relatively slower receiver rotor 91a is capable of following or tracking its transmitter rotor 90a at all times.

Type wheel aligner.—Although the type wheels shown in Figs. 12-15, inclusive, follow the servo motor and the final weight indications of the pointers 61 and 62 with great accuracy under the influence of the servomotors 94 and 96, the nature of the mechanism is such that at a condition of scale balance, the type wheels normally are not aligned properly to print in a straight line. An example of such misalignment is shown in Fig. 15 wherein, not only are the digits out of line but the center line, with reference to which the printing is accomplished, is straddled by two weight indications, for example, 29995 and 30005.

Thus it is necessary to provide a special mechanism for aligning such type wheels to prepare same for printing and also to insure that the proper digits thereof are selected which are to be brought into line especially in those situations where fine perception is needed in digit selection, as in the cases of digits straddling the center line, an example of which is shown in Fig. 15.

In general, the aligning of the type wheels is accomplished by means of the above-described star wheels, which are fixed to said type wheels, in combination with aligning fingers having pointed extremities which are insertable into the notches of the star wheels. Such aligning fingers do not operate simultaneously but rather in succession, whereby the type wheel elements 228, 231, 233 and 240 are sequentially or consecutively aligned.

The consecutively operative aligning fingers are indicated in Fig. 16 as at 250, 251, 252 and 253, the pointed extremities of which are adapted respectively for cooperating with the star wheels 230, 234, 238 and 243. Said aligning fingers 250-253, inclusive, are mounted for individual angular movement upon a common pivot rod 254 intermediate the finger extremities. Said fingers are respectively urged in a clockwise direction, as viewed in Fig. 16, by means of springs 255, 256, 257 and 258 which preferably are secured to the upper extremities of said fingers.

The mechanism for sequentially or consecutively urging the points of said aligning fingers into engagement with their respective star wheels comprises, in the form shown, a plurality of cams, one for each of the fingers, as at 259, 260, 261 and 262. Said cams are mounted upon a common shaft 262a for angular motion therewith. The profiles of said cams are so formed that the aligning fingers will be urged in a counterclockwise direction against the influence of said springs in consecutive order commencing with the finger 250, thereafter finger 251 and so on.

It is desirable, of course, to actuate the align-

ing fingers 250-253, inclusive, immediately after the apparatus has reached its correct indication, that is, immediately after the visual indicator 61, 62 indicates a proper weight indication.

Another way of expressing this is that it is desirable to actuate said aligning fingers immediately after the output of the force measuring cells has been balanced against a counteracting output in the null system. Said aligning fingers 250-253 are consecutively actuated in response to the pressing of the button of switch 82 by virtue of the following operative interconnection: the print motor 154 is actuated in response to the momentary closing of the print switch 82 whereby the main power shaft 216 (Figs. 10, 11) is caused to rotate through a preselected angular increment, for example, 360°. The angular motion of the said shaft 216 is employed for sequentially actuating said aligning fingers 250-253 by means of a cam 263 which is rigidly attached for rotation with said shaft 216, the cam 263 cooperating with a roller 264 secured to an arm 265, the latter being angularly shiftable about the above-described hinge rod 191. Consequently rotation of cam 263 through 360° will angularly shift the arm 265 through a preselected angular increment depending upon the profile of said cam. Such angular movement of the arm 265 is communicated to the cams 259-262, inclusive, by means partially shown in Fig. 10 and shown in detail in Fig. 16, and which comprise a crank lever 266 pivotally mounted upon said hinge rod 191 and provided with arms 266a and 266b. The latter arm is positioned for engagement with a ledge portion 265a of the arm 265 in such a manner that when the latter arm is raised by the cam 263, its upper angular motion is communicated to the arm 266b, thereby shifting the arm 266a in a clockwise direction, as viewed in Fig. 16. Arm 266a by means of a connecting link 267 controls the angular motion of a sector gear 268 which is normally urged against a suitable limit stop in a counterclockwise direction (Fig. 16) by means of a spring 269. The toothed sector portion 268a is positioned for engagement with the gear 270 which is rigidly secured to the above-described cam shaft 262a. The actuation of the sector gear 268 by means of the print motor 154 through the above-described linkage is accomplished, of course, against the influence of the spring 269 which returns said cams to the position shown in Fig. 16 after cam 263 has moved through 360°.

In order to illustrate the selectivity of the type wheel aligning mechanism, assume that the weight upon the platform is 29,997½ lbs. The apparatus is designed to indicate to the nearest 5 lbs. which in this case might be either 29,995 or 30,000. With reference to a center line 271 of the hammers or platens, Fig. 15, the digits of the type wheel may be lined up as shown in Figs. 15 and 16. Fig. 15 represents a printing of the digits in the neighborhood of said center line although in fact the printing mechanism is not designed for printing digits which are so far removed from said center line. With the type wheels so aligned, the cam shaft 262a is actuated in a manner above described by pressing the printing push button of switch 82. Said cam shaft 262a is thereupon angularly shifted in the direction of the arrow 262b and first the point of finger 250 is thrust into a notch of the star wheel 230. This will center either 95 or 00 relative to the center line 271 (Fig. 15). In the position shown in Fig. 16, the point of the finger

251 is exactly in line with a point of the star wheel 234. If the finger 250 pulls into alignment the numeral 9, the point of the star wheel 234, which is opposite to the point of the finger 251, will be moved through the gear train interconnecting said type wheel elements in such a manner that said finger 251 will, when the cam shaft 263 is further turned, enter a notch in the star wheel 234 whereby digit 9 will be centered. If, on the other hand, finger 250 centers digits 00 over line 271, the star wheel 234 will be angularly shifted such that its aligning finger 251 will contact the opposite side of such above-mentioned star wheel point on wheel 306 and will enter a notch whereby the digit 0 of the type wheel 232 will be centered on line 271.

In order to be able to align the digits on type wheel elements 228 and 231 by means of said aligning fingers 250 and 251, it is necessary to have flexibility in the gear train which interconnects said two type wheel elements. In the form shown, this is accomplished by a so-called double gear unit 272 which is indicated in detail in Figs. 17 and 18. Its location in the geared interconnection between said type wheel elements is shown in Fig. 13. With reference to Fig. 13, it will be seen that when the type wheel element 228 has been rigidly aligned by means of the finger 250, the type wheel element 231 would also be rigidly held in position by virtue of the geared interconnection therebetween. The interposition of the so-called double gear unit 272 permits the type wheel element 231 to be slightly shifted angularly by the aligning finger 251 in spite of the rigid indexing or holding of the type wheel element 228. The double gear unit 272 in general comprises a pair of gears which are resiliently associated by, for example, suitable spring means, as shown in Figs. 17 and 18. For ordinary operation the gears are in fixed relation but can be varied from such position by compression of said spring means. Referring to Figs. 17 and 18, the flexible double gear unit 272 is constituted by two gears 273 and 274 which are mounted upon a bushing 275 and provided with a spacer interposed therebetween as at 276. Said gears and spacer are locked upon said bushing, for example, by means of a removable locking ring 275a. Each of the gears 273 and 274 is provided with an inwardly extending pin, said pins being respectively indicated at 277 and 278. Said pins extend respectively into arcuate slots 279 and 280 formed in the spacer 276. The pins 277 and 278 are inserted into said slots, and the latter are so positioned that said pins abut preferably the clockwise extremities of their respective slots, as shown in Fig. 18, where they are resiliently urged against such extremities by suitable resilient means, for example, helical compression springs as at 281 and 282, respectively in the slots 279 and 280.

In order to provide a means for making fine adjustment of the permanent alignment between the type wheel elements 228 and 231, suitable means are provided for adjusting the relative positions of the gears 273 and 274 of the resilient double gear unit 272. Said means, for example, comprise set screws 283 and 284 which are received in suitable threaded bores in the spacer 276 and which are positioned respectively for acting upon the pins 277 and 278 whereby angular adjustment of said set screws can adjust the relative positions of the gears 273 and 274.

By providing means for adjusting the relative

angular positions of said gears 273 and 274, it becomes unnecessary to make adjustments of the alignment of the drive gears 229 and 233 with their respective type wheels. If desired, suitable locking screws, as at 283a and 284a, can be provided for locking said screws 283 and 284, respectively, after an adjustment has been made.

The type wheel elements 236 and 240, together with their respective star wheels 238 and 243 and their associated aligning fingers, operate in exactly the same way as those above described.

Preferably the aligning finger cams 259-262, inclusive, are so adjusted that the finger 250 fully engages the star wheel 230 before the next succeeding aligning finger 251 starts its angular movement and the same is true with respect to the succeeding star wheels and their aligning fingers.

Aligner interconnection between coarse and fine type wheel groups 87a and 87b.—In the absence of special interconnecting mechanism, when the type wheel element 231 is aligned by its finger 251, there is no resulting movement in the type wheel element 236. Consequently it is necessary to provide special means for operatively interconnecting the type wheel elements 231 and 236 in order to prevent the aligning finger 252 from engaging the wrong side of a point in star wheel 238 whereby the printer is caused to print with an error of 1,000 lbs. This problem arises when a selection is made between 0 and 9 on type wheel 232, that is, finger 251 selects a notch on star wheel 234 which will align either of the digits 0 or 9 of its associated type wheel.

Where the platen center line 271 is substantially straddled by a pair of digits upon the type wheel 237 in such a manner that it is doubtful which one will be selected by the aligning finger 252, the operative interconnection between the type wheel elements 231 and 236 is effective to shift the type wheel 237 slightly angularly such that, if the 9 of wheel 232 is centered relative to said center line 271, the lower of the digits on type wheel 237 is similarly centered. Similarly if the 0 on type wheel 232 is centered by finger 251, the higher, for example, representing 10 instead of 9 of the two digits on type wheel 237 is centered.

In order to accomplish the above purpose, the cam 235 is secured to the type wheel 232, as viewed in Figs. 12, 19 and 20. Cam 235 comprises a semi-cylindrical surface which has an angular extent of 180° as shown in detail in Fig. 20. A critical or drop point of this cam is designated as at 235a and is positioned in preselected angular relationship to the digits 0 and 9 upon the type wheel 232 for cooperation with a cam follower 285 which, under certain circumstances to appear below, positions a star wheel pusher finger 286 for engagement with the star wheel 236 whereby as the aligning finger 251 descends or is thrust into the star wheel 234, there is simultaneously an angular shifting of the next successive star wheel 236.

The cam follower 285 is pivotally secured to the side of aligning finger 251. The point of cam follower 285 which actually engaged the cam 235 is designated as 285a. Pivotally secured to the cam follower 285 is the above-mentioned star wheel pusher finger 286 which is urged against a limit stop 287 upon said follower 285 by means of a spring 288, one extremity of which is secured to a portion of the finger 286 and the opposite extremity of which is secured to a portion of the cam follower 285. The latter is urged upwardly,

as viewed in Fig. 21 against a limit stop 289 by means of a spring 290, one extremity of which is secured to said follower 285 and the opposite extremity of which is secured to the aligning finger 251.

Referring to Fig. 16, the operation of the aligner interconnection is as follows: When finger 251 indexes the star wheel 234 whereby the digit zero of the type wheel 232 is centered on line 271, the point 285a of the cam follower 285 will miss the critical point 235a of the cam 235, and the point of the star wheel pusher finger 286 will miss engagement with the star wheel 233. By means of the receiver 93, the type wheel 237 is adjusted with the zero digit almost in position to print in such a way that when the aligning finger 252 is actuated it will engage a notch in star wheel 238 whereby the zero digit will be centered. On the other hand, if the aligning finger 251 engages such a notch in its star wheel 234 that the digit 9 on its type wheel commences to be moved into a central or printed position, the point 285a of the cam follower 285 will contact the critical point 235a of the cam 235 whereby said cam follower 285 will be shifted in a counterclockwise direction, as viewed in Fig. 21, against the influence of the spring 290. Thus the star wheel pusher finger 286 will be urged toward the star wheel 238 and will contact a point of such star wheel, and as the aligning finger 251 moves inwardly of the star wheel 234, such pusher finger 286 will angularly shift the star wheel 238 and thus its associated type wheel 237 in such a way that the digit 9 thereupon will be angularly shifted nearly into a centralized position relative to said center line 271. Immediately thereafter when the aligning finger 252 is angularly shifted inwardly of its star wheel, it will select the proper notch therein whereby said digit 9 will be aligned for printing.

It is understood that although the above description relates to the action of this mechanism with regard to the selection of digits 9 and 0 of the type wheel 237 in response to the selection of digits 9 and 0 upon type wheel 232, similar selective action can occur by means of the mechanism between any two consecutive digits upon the type wheel 237 in response to the selection of any two consecutive digits upon the type wheel 232.

Because of the above-described novel mechanism for indexing the type wheels and for operatively associating the two groups of type wheels 87a and 87b (Fig. 12), as by the aligner interconnection, small inaccuracies in the self-synchronous repeater systems and small amounts of backlash in the connected gearing can be tolerated without causing misprints.

Ticket holder and indexing device therefor

The ticket holder 73 has been briefly described above in connection with Fig. 1. It is indicated in detail in Fig. 23 which shows it in combination with the mechanism for automatically advancing it for the printing of lines 1, 2 and 3 of the scale ticket 63.

In general, it is desired to mount the ticket holder 73 in such a way that it can be easily withdrawn to an inactive position from any of its several active or printing positions, one of which is shown in Fig. 1. Holder 73 is shown in an inactive position in Fig. 23 at the righthand portion thereof. Mechanism is provided for maintaining the clamp 73, and the ticket 63 held thereby, in a so-called "square position" relative to the printing device, that is, with a side edge 75

of such ticket perpendicular to the platen center line 271 (Fig. 15) while the clamp is being advanced or withdrawn.

Furthermore, it is desired to render the print motor 154 (Fig. 3), which moves holder 73, inoperative and to extinguish the signal lamp 83 whenever the holder 73 is in a withdrawn position, as shown in Fig. 23, and also after the printing apparatus has completed printing of data upon the last line of the scale ticket 63. The print motor 154, as above explained in connection with Fig. 3, is under the influence of the "stop-run" switch 81, the print switch 82, the ticket microswitch 83a, and the motor control microswitch 157. When the apparatus is in operation the switch 81 is closed and the actuation of the motor 154 depends upon the switches 82 and 83a. The former of these switches is normally open and from a consideration of Fig. 3 it will be seen that the closing of such switch 82 will be ineffective so long as the ticket microswitch 83a is open. Mechanism is provided for maintaining said switch 83a normally in an open condition, that is, when the ticket holder 73 is moved rearwardly from position 1, as viewed in Fig. 1. Said ticket microswitch is moved to a closed position when the ticket holder is in position for printing upon lines (1) (2) or (3) and after (3) has been printed, switch 83a is automatically opened. The signal lamp 83 is extinguished whenever said switch 83a is opened.

The mechanism for mounting the ticket holder 73 upon the front cover 190b of the printer 56 for sliding movement relative thereto over the horizontal top surface 190c thereof comprises, in the form shown, a pair of downwardly extending brackets 300, only one of which is shown in Fig. 23. Each of such brackets extends downwardly through the slots 76 and 77 formed in the horizontal surface 190c. Journalled in said brackets 300 is a shaft 301 which extends between said slots 76 and 77 and has rigidly secured to each extremity thereof one of a pair of pinions 302, each of which is adapted for meshing with one of a pair of racks 303, the latter being mounted underneath surface 190c along an edge of each of the slots 76 and 77. By means of this rack and pinion mechanism the ticket holder 73 is maintained at all times perpendicular to the slots 76 and 77 whereby a ticket when advanced and withdrawn is held in proper alignment.

Secured to one of the brackets 300 is a finger 300a which, in the form shown, extends horizontally when the ticket holder is in position for printing, as is shown in its leftmost position in broken lines in Fig. 23. The purpose of the finger 300a is to engage a portion of a signature printing platen after line (1) of the scale ticket has been printed, whereby such platen is rendered inoperative during the printing of lines (2) and (3), as will be described below in connection with Figs. 26 and 27.

Also secured to the shaft 301 is a pair of rollers 304, one each being secured adjacent the extremities of the shaft for the purpose of cooperating with a rounded corner portion 190d of the front cover 190b, whereby the tilting and opening of the ticket holder 73 is facilitated, as shown in the righthand portion of Fig. 23.

In the latter figure the ticket holder 73 is shown in two positions, namely, at "O," which is the position for opening the clamp for insertion or removal of the ticket, and at "P," which is the position for the printing of the top line (line (1)) of the scale ticket. When the

holder 73 is pulled toward the operator by handle 75 to its extreme position, the rollers 304 will engage the curved corner surface 190d, whereupon the ticket holder will swing in a clockwise direction (Fig. 23) through an arc of, for example, 30 to 40° whereupon the brackets 300 will strike the ends of the slots 76 and the holder 73 can be opened by pushing down upon the handle 75. Such tilting of the ticket holder raises the mouth thereof, whereby the scale ticket can be more conveniently inserted or removed.

The ticket holder indexing mechanism proper is constituted by an index disk 305 mounted for angular movement upon a suitable shaft 306 which is journaled in suitable supporting plates, as at 307. The index disk 305 is provided with a radially extending slot 308 having an opening on the periphery of said disk. The latter can be positioned whereby said slot can engage the above-mentioned shaft 301, associated with the ticket holder, and can advance said shaft and holder successively in response to successive increments of angular motion of the disk 305.

Means are provided for yieldingly holding index disk 305 in a plurality of preselected angular positions which correspond to the three positions for the printing of such three lines of the scale ticket, and also in another position wherein the slot 308 is positioned for the insertion or removal of the shaft 301. Such means, in the form shown, constitute a pawl and notch mechanism, the notches being formed on the periphery of the index disk 305. Such notches are indicated as at 309, 310, 311 and 312. Said notches are yieldingly engaged by the point of a pawl 313 which is resiliently urged toward the disk 305 by suitable means, such as a spring 314. Thus the pawl 313 is adapted for indexing and yieldingly holding the disk 305 in any one of a plurality of angular positions which, in the form shown, are four in number. When the notch 309 is engaged by the pawl 313, the slot 308 is angularly located to permit the insertion or the removal of the shaft 301 whereby the ticket holder 73 can be moved into or out of operative engagement with the disk 305. In view of the yielding nature of the indexing of the disk 305 in this initial position, it is possible, by thrusting upon the ticket holder 73 to the left, as viewed in Fig. 23, to urge same to its first position for the printing of line (1) of the scale ticket. Such manual thrust will move the point of the pawl 313 out of the notch 309 and into the notch 310 whereupon rod 301 assumes position (a). It is desired to provide a suitable limit stop at this angular position of disk 305 to prevent further forward movement of the ticket holder and its scale ticket. For this purpose a limit stop lever 315 is pivotally mounted upon the disk 305 at 316 and is resiliently urged against a limit stop pin 317 on disk 305 by a spring 318. The lever 315 is so constructed and arranged that an extremity 315a thereof extends beyond the periphery of the disk 305 in a position for engagement with a movable limit stop finger 319 which is mounted upon an eccentric 320. Upon rotation of the latter, the finger 319 will move out of the range of the extremity 315a whereby the index disk 305 can be angularly advanced by means of a thrust finger 321 which preferably also is mounted upon the eccentric 320 and which can be, as is shown, integral with the finger 319. The thrust finger 321 is positioned between a pair of pins 322 in such a manner that when the eccentric 320 is

rotated, a rocking and pushing action will be imparted to the thrust finger 321. An extremity 321a of said finger 321 under the influence of said rocking and pushing action is adapted for engaging, when first actuated, a tooth 323 formed in the disk 305, whereupon, after the disengagement of lever 315 and finger 329, the pawl 313 is urged out of the notch 310, and the disk 305 is angularly shifted until the next successive notch 311 is engaged by said pawl and rod 301 is shifted to position (b) for printing line (2). The disk 305 is thus moved to and indexed in its next successive angular position, whereupon the thrust finger 321 will assume its original position, as shown in Fig. 23. Such actuation of thrust finger 321 is accomplished by a single revolution of the eccentric 320. The next successive revolution of said eccentric causes the thrust finger 321 to engage a next successive tooth 324 formed on the disk 305 whereby the notch 312 is moved into engagement with the pawl 313, the disk 305 further advanced by a preselected angular increment, and rod 301 is advanced to position (c) for printing line (3).

25 A portion of the disk 305 adjacent the tooth 324 is cut away, as at 325, whereby succeeding actuations of the thrust finger 321 are ineffective to advance the disk 305 further.

When the notches 310, 311 and 312 are indexed 30 by the pawl 313, it will be understood that the ticket holder 73 respectively is positioned for printing of lines (1), (2) and (3).

35 The eccentric 320 is rotated through one revolution by means of the print motor 154 via the main power shaft 216 which, as above explained, upon each momentary closing of switch 82 is moved through 360°. The shaft 216 is drivably associated with the eccentric 320 by means of gears 326 and 327 which have the same number 40 of teeth and which are interconnected by an idler gear 328. The eccentric 320 and the gear 327 are rigidly mounted upon a common shaft 329.

45 As above explained, it is desirable for the common power means for actuating the printing mechanism, that is, actuating the platens or hammers 213, and the ticket indexing mechanism, to be inoperative whenever the ticket holder 73 is withdrawn from a position wherein 50 one of the lines (1), (2) or (3) cannot be printed. Also it is desired for said power means to be inoperative after line (3) of the scale ticket has 55 been printed. The means for accomplishing this are also indicated in Figs. 23-25, inclusive, and include a cam mechanism indicated generally at 330 in Fig. 25 for governing the ticket microswitch 83a (Fig. 3). This cam mechanism is constituted by a cam 331 which cooperates 60 when an arm 332 which mounts a roller 333 for riding upon said cam. The cam 331 is operatively associated with the ticket indexing mechanism above described by means of a cam control disk 334 which preferably is formed integral with the shaft 306, said cam 331 being rigidly secured 65 to the shaft 306, as shown in Fig. 24.

The cam control disk 334 is fixed in a preselected angular position relative to the cam 331 and said disk is provided with a plurality of indexing notches which, for a purpose to appear hereinafter, is equal to the number of notches in the index disk 305 plus one. Such notches in the cam control disk 334 are spaced at intervals equal to those in index disk 305 whereby corresponding pairs of notches in said disks can be in register, as shown in Fig. 23a. Such notches are

indicated in cam control disk 334 at 335, 336, 337, 338 and 339. Normally such corresponding pairs of notches are held in register because said disks are yieldingly held in a preselected angular relation, for example, by means of a spring 340 which urges the disk 334 against a limit stop pin 341, said spring 340 having its opposite extremities secured to respective of said disks.

When the notch 335 of disk 334 is indexed by pawl 313, and when notch 309 is in register therewith, the slot 308 is positioned for insertion or removal of the shaft 301, and cam 331 is in such a position that the roller 333 rides upon a high portion of said cam and the ticket microswitch 83a is held in an open position by means of the arm 332. However, when the shaft 301 of the ticket holder 73 is moved into the slot 308 of disk 305 and said ticket holder is thrust inwardly to the position shown at "P" (Fig. 23), disk 305 is advanced angularly and the cam control disk 334 is angularly shifted by virtue of the spring interconnection 340 to the position shown in Fig. 23 whereby the notch 336 is indexed jointly with the notch 310 by the pawl 313. During such shifting of the disks 305 and 334, the latter is held against the limit stop pin 341.

The cam control disk 334 upon movement to the position shown in Fig. 23, angularly shifts the cam 331 to the position shown in Fig. 25 wherein the roller 333 rides onto a low portion of the cam and the ticket microswitch 83a is thereupon closed and print switch 82 then can start motor 154. The angular extent of such low portion of the cam 331 is adequate in extent to maintain the switch 83a in a closed position when the cam control disk 334 is angularly shifted for the indexing, by such pawl, of the notches 337 and 338 which respectively correspond to the positions of the ticket holder 73 for the printing of lines (2) and (3).

Such angular shifting of the cam control disk 334 is also accomplished by the above-described thrust finger 321 through the intermediary of teeth 342 and 343 (Figs. 23 and 23a), such teeth being normally in alignment with their respective counterparts 323 and 324 in the disk 305.

When the notches 312 and 338 are jointly indexed by pawl 313, the cam roller 333 will have reached the extremity of the low portion of the cam 331, and although the switch 83a is closed in this situation, any further movement of the cam control disk 334 will force the roller 333 to a high part of said cam 331, whereby the switch 83a will be opened and print switch 82a thus rendered inoperative. In view of the fact that it is not desired to shift the index disk 305 through any further angular increments for the advancing of the ticket holder after line (3) has been printed, the above-described cutaway portion 325 is formed in the disk 305. However, the first momentary closing of the print switch 82 after the notches 312, 338 have been indexed accomplishes a printing upon line (3) and immediately thereafter the thrust finger 321 engages a tooth 344 of the cam control disk 334 and advances it to a point where the notch 339 is moved up into register with the notch 312 whereupon the pawl 313 yieldingly engages both of said notches. Such shifting of the cam control disk 334 through this final angular increment effects an opening of the switch 83a via the cam 331, whereby the print switch 82 is rendered inoperative. Consequently after line (3) has been printed, any further closing of the switch 82 will be ineffective

until the ticket holder and its rod 301 is withdrawn from position (c), Fig. 23.

In order to maintain an indexing relationship between pawl 313 and notch 312 during the above-described final shifting of the disk 334 wherein notch 339 is shifted into register with notch 312, the radius of cam control disk 334 is preferably slightly less than that of the disk 305 at least over that portion of the periphery of disk 334 between the notches 338 and 339. Thus the point of the pawl 313 will not be lifted entirely out of the notch 312 by such final angular movement of the cam control disk 334.

From the above it will be seen that both disks 305 and 334 are simultaneously angularly shifted through a common angular increment from ticket printing position (1) to position (2), and thereafter from position (2) to position (3). This is accomplished by means of the aligned pairs of teeth 323, 342 and 324, 343. Thereafter, in view of the absence of further teeth upon the disk 305, only the disk 334 will be advanced by action of the thrust finger 321 on the tooth 344.

By means of the above control mechanism for switch 83a, it is impossible to print twice on line (3) of the scale ticket. It is to be understood that the ticket holder 73 can be manually moved to position "O" after either one, two or three lines have been printed.

Signature platen or hammer.—Referring now to Figs. 10, 26 and 27, a platen is provided as at 350 for the purpose of striking toward the facsimile signature slug 207 whereby the signature of the weigh master automatically can be printed in the space 72 of the scale ticket 63 (Fig. 2) simultaneously with the printing of line (1) of said ticket. The signature platen is mounted in a manner analogous to the above-described platens 213 and 213a (Figs. 10 and 11), that is, said platen is mounted for pivotal movement upon the rod 219 by means of arms as at 350a which rest upon the cross rod 223. Movement of the latter rod is controlled by the cam 226 acting on the lever 222 in the manner above described concerning Fig. 11.

It is desired to print the facsimile signature only once upon each scale ticket 63, namely, at the time that line (1) of the ticket is printed, and not when lines (2) and (3) are printed.

The means for accomplishing this, in the form shown, comprise a device for holding the signature platen in its normal position at rest, as indicated in Fig. 26, after line 1 has been printed. By such means the arms 350a are prevented from descending when the cross rod 223 is thrust downwardly. Consequently when said cross rod is released it cannot throw the platen 350 upwardly against the scale ticket. The means for holding the platen 350 in such an inoperative position are shown in Figs. 23, 26 and 27 and comprise a rod 351 secured to the platen 350 preferably near the outer extremity thereof which is positioned for cooperation with the finger 300a described in connection with Fig. 23. The finger 300a is indicated in Fig. 23 in three different positions indicated by numerals I, II and III. When said finger is in position I, it is not located beneath the rod 351. Thus the platen 350 can operate normally for the printing of the facsimile signature in response to the actuation of the print motor. This occurs simultaneously with the printing of line (1) when the ticket holder 73 is in position "P" (Fig. 23). However, when the ticket holder is advanced for the printing

of either line (2) or (3), the finger 300a is advanced respectively to position II or III, in each of which positions said finger 300a is beneath the rod 351, thereby holding platen 350 inoperative for printing purposes.

Carbon ribbon indexing mechanism.—The mechanism for pulling the carbon ribbon web 193a (Fig. 9) in preselected increments is indicated generally at 197 in Fig. 10 and is shown in greater detail in Figs. 28 and 29. It consists of a main roll member 352 over which the web 193 passes and against which said web is urged by means of a pressure roller 353 mounted upon an arm 354 the latter being pivoted at 355. Said pressure roller 353 is urged against the main roll 352, for example, by means of a spring 355a which is secured to the lower extremity of said arm 354 and to a suitable fixed support, for example, a support side wall 356 which in turn is secured to base plate 190a.

The main roll 352 is advanced angularly in preselected increments by means of a ratchet mechanism indicated generally at 357, in response to the momentary closing of the print switch 82, through the intermediary of an arm 358, the outer extremity 358a of which is in the path of motion of the arm 265 (Fig. 10) which actuates the type wheel aligning mechanism.

The carbon ribbon indexing unit 197 preferably discharges the used ribbon through an opening 359 in the bottom thereof, the web 193a being guided to said opening by suitable guide plates 360 secured as to a base 360a of the carbon ribbon indexing device.

The above-mentioned ratchet mechanism 357 comprises a ratchet wheel 361 which is rigidly mounted upon a shaft 362, the latter supporting the main roll 352 and being secured thereto for movement therewith. The ratchet wheel 361 is locked against reverse movement by means of a locking pawl 363 which is pivoted in a conventional manner and urged against the ratchet wheel by means of a spring 364. The ratchet wheel is advanced angularly in a direction to move the web 193a in the direction of the arrow (Fig. 29) by means of an advancing pawl 365 which is mounted upon the arm 358. The latter is pivotally mounted upon a suitable pivot pin 366 which in turn is supported by side walls 356 of the mechanism. The advancing pawl 365 is resiliently urged against the wheel 361 by means of a spring 367. And the under surface 358b of the extremity 358a of arm 358 is resiliently urged to rest upon the arm 265 (Fig. 10), for example, by means of a spring 368.

If desired, a knurled hand knob as at 369 can be secured to the shaft 362 of the main roll 352 whereby the carbon ribbon web can be moved manually.

In operation, the apparatus is first energized by closing the on-off switch 78 and moving the Stop-Run switch 81 to the "Run" position. It is assumed that the visual indicator pointers 61, 62 are initially in a zero scale position, there being no load upon the platform 50.

A load, such as a draft of livestock, is placed upon the platform 50 whereupon a stress is applied to the weighing cells 51 which produces an unbalance of the individual bridge circuits of said cells, and results in an output voltage from each cell which is totalized in the above-described totalizing circuit to produce a total cell output voltage $e_s = f_i W_t$.

When there is no load upon the platform 50, of course, $e_s = 0$. Hence the input to the amplifier

105 (Fig. 4) is 0 and the servomotor 84 is inoperative. However, the voltage e_s , caused by the above load on the platform, is applied to the amplifier 105 and actuates the servomotor 84, whereby the slide wire element 85 is actuated to direct the balancing voltage e_b into the circuit. When the balancing voltage e_b is equal to the cell voltage e_s , the input voltage e_i to the amplifier 105 is reduced to 0 and the servomotor 84 is arrested.

The weigh master, after examining the draft of livestock, adjusts the knobs 68b, 69a, 69b, 70a and 70b on the printer 56 in order to adjust the type wheels governed thereby to print (a) the species of the livestock, (b) the number of individuals, and (c) the symbol of the commission agent.

When the dials 61 and 62 have come to rest and indicate the weight of the load, the weight type wheels 87a, 87b (Fig. 3) will substantially simultaneously reach their weight indication through the intermediary of the synchro systems 88, 89 above described. The weigh master at this point or previously inserts the scale ticket 93 into the holder 73 and moves same to the position shown in Fig. 1 for the printing of line (1). When the scale ticket is in position for printing, the weigh master closes the print switch 82 by pressing the push button connected therewith whereupon the following occurs: The circuit of the print motor 154 is momentarily energized for a sufficient length of time to close switch 157 via cam 157a. Motor 154 through the gear train 215 drives the main power shaft 216 through the clutch 217 which is energized by the solenoid 218 in response to the energizing of the print motor circuit. The main power shaft 216 turns through 360° whereupon the motor 154 is deenergized by an opening of the switch 157 under the influence of said cam 157a.

During the single revolution of the main power shaft 216 the following take place in the order named:

(1) The digits upon the type wheels of the weight unit are aligned because of the actuation of arm 265 by the cam 263 which, referring to Fig. 16, shifts the sector gear 268 in a clockwise direction.

(2) During the upward thrust of arm 265 (Fig. 10) under the influence of cam 263, the carbon ribbon indexing unit 197 is effective to pull the carbon ribbon web 193a through a preselected distance preparatory to the printing of the scale ticket. This is accomplished by the actuation of the ratchet arm 358 which rests upon said arm 265.

(3) Simultaneous with the actuation of the type wheel aligning mechanism, the platen control cam 226 (Fig. 11) is angularly shifted and when the digits of the weight unit type wheels 60 are aligned, the printing platens are thrown against all of the type wheels after arm 222a reaches the crest or high point 226a of cam 226 and suddenly rides off said cam.

(4) After the printing of line (1) has taken place, the indexing unit of Figs. 23-25 is actuated to advance the ticket holder 73 from its first position, as shown at (a) or "P," to position (b) for the printing of line (2). In position (b) the signature platen is rendered inoperative by the movement of finger 300a beneath the signature platen rod 351.

Holder 73 is similarly advanced from position (b) to position (c) after line (2) is printed.

There is thus provided novel means for the measurement of a force, such as weight. The

apparatus has many advantages in that the visual indicator 53 can be placed in any location near or remote relative to the weighing cells and, of course, the printing device 56 can also be placed in any desired location near or remote relative to the indicator or weighing cells. No mechanical connection is necessary between the weighing cells 51, the indicator 53 or the printing device 56 in that only electrical connecting cables are required. The speed of the visual indicating device is extremely high, requiring less than three seconds to go from a zero indication to a fully stabilized maximum indication. The weight indicating portion of the printing device 56 will follow the visual indicator and become stabilized within substantially the same time. Such high speed is particularly advantageous where the load to be weighed is moving, that is, in so-called "dynamic weighing," and also in those cases wherein the object to be weighed is on the platform only a very short time, such as five or six seconds. Moreover, the speed of the indication of the apparatus can be controlled, as in the form shown, by manually actuated dampening means. This is advantageous where the above described random acceleration loads are placed upon the platform, for example, as caused by the milling or stamping of livestock on the platform. Where large loads accompanied by such random accelerations are being weighed, it is usually desired to have the indicating device come up to weight rapidly and thereupon to apply additional dampening to minimize or eliminate any oscillations of the load indicating means.

Thus the apparatus can be employed for measuring automatically a physical quantity, such as force, which can be converted to a variable electrical parameter, the latter being inserted into a null device. The term "electrical parameter" as employed herein refers to, for example, resistance.

Various changes may be made in the design and arrangement of the parts without departing from the spirit and scope of the invention as the same may now be understood by those skilled in the art. For a definition of the limits of the invention, reference will be had primarily to the appended claims.

What is claimed is:

1. In a device of the class described, the combination including: a force sensitive device including means for producing an electrical signal responsive to a force applied thereto; a balance signal producing device electrically associated in a circuit with said force sensitive device for balancing said signals in such circuit, said balancing signal producing device including power means operative in response to the degree of unbalance of said signals; a fine indicia element; a coarse indicia element mechanically separate from said fine element; and separate self-synchronous repeater systems, each having a transmitter and a receiver, for operatively interconnecting said fine and coarse indicia elements with said power means, the transmitters of said systems being drivably associated with said power means and with each other for rotation at a preselected speed ratio.

2. A weighing device having in combination: a weighing cell containing stress receiving column means, the latter carrying electrical resistance type strain gauge means bonded thereto; an electrical circuit connected with said strain gauge means for measuring change in an electrical

characteristic of such gauge means and producing a signal in response thereto, such change being responsive to the stress received by said column means; a signal indicator element including a sub-element for coarse indication of such signal and another sub-element for fine indication of such signal, said sub-elements being operatively interconnected for movement in a preselected speed ratio, the sub-element for fine indication of the signal being relatively faster than the other sub-element; a device for operatively interconnecting said circuit and said indicator element whereby changes in such electrical characteristic as measured in said electrical circuit are converted into a signal indication by said indicator element; a stress indicia device including a first indicia portion for indications responsive to indications of said coarse sub-element and another indicia portion for indications responsive to indications of said fine sub-element; a synchro system having a transmitter and receiver, the transmitter being drivably associated with said coarse sub-element, said first indicia portion being operative in response to the receiver of said system; a separate synchro system having a transmitter and a receiver, such transmitter being drivably associated with said fine sub-element, said other indicia portion being operative in response to the receiver of said last mentioned synchro system; and means for introducing a tare correction to said indicator element in response to a residual stress upon said weighing cell comprising a device for actuating said indicator element in response to an electrical signal from said second-mentioned synchro system arising from such residual stress.

3. A weighing device having in combination: a weighing cell containing stress receiving column means, the latter carrying electrical resistance type strain gauge means bonded thereto; an electrical circuit connected with said strain gauge means for measuring change in an electrical characteristic of such means and producing a signal in response thereto, such change being responsive to the stress received by said column means; a signal responsive element including a coarse sub-element for rough response to such signal and a fine sub-element for fine response to such signal, said sub-elements being operatively interconnected for movement in a preselected speed ratio, the fine sub-element being relatively faster than the other sub-element; a device for operatively interconnecting said circuit and said element whereby changes in such electrical characteristic as measured in said electrical circuit actuate said sub-elements; a stress indicia device including a first portion for indications responsive to said coarse sub-element and another indicia portion for indications responsive to said fine sub-element; a synchro system having a transmitter and receiver, the transmitter being drivably associated with said coarse sub-element, said first indicia portion being operative in response to the receiver of said system; a separate synchro system having a transmitter and a receiver, such transmitter being drivably associated with said fine sub-element, said other indicia portion being operative in response to the receiver of said last-mentioned synchro system; and means responsive to an electrical signal from said last-mentioned transmitter for governing said fine sub-element for correcting the response thereof in accordance with residual stress upon said cell.

4. In apparatus of the class described, a weight

sensitive device comprising weighing cell means containing stress receiving column means, the latter carrying resistance type strain gauge means bonded thereto and adapted for use with a weighing platform; an electrical circuit for measuring an electrical output signal of said cell means, said output being proportional to the stress upon said column means; a signal responsive element; a device for operatively interconnecting said circuit and said element; said element including a fine sub-element and a coarse sub-element; a stress indicia device including a fine indicia portion for indications responsive to said fine sub-element, and a coarse indicia portion for indications responsive to said coarse sub-element; a pair of reversible motors, respectively for driving said coarse and fine indicia portions; a coarse synchro transmitter and receiver system having the transmitter thereof drivably associated with said coarse sub-element, and having the receiver thereof mechanically and electrically connected to said reversible motor for driving said coarse indicia portion, said transmitter and receiver being electrically interconnected for producing a voltage when not in step with each other, which voltage is applicable to said reversible motor for urging the transmitter and receiver into step; and a separate synchro transmitter and receiver system having the transmitter thereof drivably associated with said fine sub-element, and having the receiver thereof mechanically and electrically connected to said reversible motor for driving said fine indicia portion, said transmitter and receiver also being interconnected for producing a voltage when not in step with each other, which voltage through said last-mentioned electrical interconnection is applicable to its respective reversible motor for urging the fine transmitter and receiver into step.

5. A weighing device having in combination: a plurality of weighing cells, each cell including stress receiving column means carrying strain gauge means; a weighing platform supported by said cells; an electrical circuit in which said strain gauge means are connected for producing a voltage responsive to the stress upon said cells, said circuit including null control means for adjusting to a null condition the voltage therein; a first indicator and a second indicator operatively interconnected for movement in a preselected speed ratio, said indicators being actuatable by said null control means; a first sub-indicator motor and a second sub-indicator motor, said first sub-indicator motor being actuatable in response to said first indicator by means including a synchro transmitter-receiver system, the receiver of such system being mechanically and electrically interconnected to said first sub-indicator motor; and said second sub-indicator motor being actuatable in response to the movements of said second indicator by means including a separate synchro transmitter-receiver system, said second sub-indicator motor being mechanically and electrically connected to the latter receiver.

6. In apparatus of the class described, a weighing cell containing stress receiving column means carrying electrical resistance type strain gauge means bonded thereto, such strain gauge means being interconnected in a bridge with a pair of fixed resistances, the strain gauge means comprising opposite arms of said bridge; an amplifier; a source of electrical energy for energizing a conjugate arm of said bridge, the opposite

conjugate arm of said bridge being connected to said amplifier; means for adjusting to a null condition the voltage input to said amplifier comprising a variable resistance in circuit with said amplifier and bridge, for introducing a counter-voltage, a control motor electrically connected to said amplifier and actuatable thereby, said control motor being operatively connected to said variable resistance for actuating same and adjusting the input voltage to said amplifier to such null condition; stress indicating means operatively associated with said control motor for indicating the stress to which said column means are subjected and including a fast pointer and a slow pointer interconnected for movement at a preselected speed ratio; a synchro transmitter and receiver system, the transmitter of which is drivably connected to said fast pointer; a second synchro transmitter and receiver system the transmitter of which is drivably connected to said slow pointer; stress indicia means operative in response to said first-mentioned receiver; and separate stress indicia means operative in response to said second-mentioned receiver.

7. In apparatus of the class described, a plurality of weighing cells each containing stress receiving column means carrying electrical resistance type strain gauges bonded thereto, there being at least two strain gauges in each cell which are subject to change due to stress applied to its respective column means, each cell having two other resistors, the strain gauges and resistors of each cell being connected as a bridge wherein two opposite arms of such bridge are constituted by two of said strain gauges and the other two arms of the bridge are fixed resistances; a source of electric energy for energizing a conjugate arm of said bridge; an amplifier; an opposite conjugate arm of each of said bridges being electrically connected to said amplifier; a drive motor electrically connected to said amplifier and actuatable thereby; a slide wire resistance element in circuit with said bridges and said amplifier for introducing a counter signal to the signal from said bridges and thus governing an input signal to said amplifier, said slide wire resistance being actuatable by said drive motor to restore the amplifier input signal to a null condition; an indicator drivably connected to said drive motor and displaceable in response to the number of revolutions of said motor; a dial bearing indicia positioned for cooperation with said indicator whereby the displacement of the latter can be read; a synchro transmitter operatively connected to said drive motor; a synchro receiver electrically associated with said transmitter; an amplifier for amplifying the output signal of said receiver; a plurality of type wheels bearing indicia thereupon for printing; and a motor for driving said wheels and said synchro receiver; said amplifier for said transmitter being electrically connected to said last-mentioned motor.

8. In apparatus of the class described, force sensitive means including electric resistance type strain gauge means for use with a source of electric energy; an electric circuit in which said strain gauge means are connected, there occurring in said circuit changes in electrical energy resulting from force applied to said force sensitive means; amplifier means for amplifying electrical energy in said circuit; motor means operatively connected to and energizable by energy from said amplifier means; electrical balancing means in circuit with said first mentioned circuit

for introducing a balancing signal of electric energy therein, said balancing means being controlled by said motor means; and means operative in response to said motor means for introducing a dampening electric signal into said circuit.

9. In apparatus of the class described, the combination comprising: force sensitive electro-responsive means for producing an electric signal in response to force applied to said means; an electric null system including a circuit connected to said means, balance signal control means, including servomotor means responsive to the degree of balance of the signals in said system, said servomotor means governing said control means; and a printing device including: type indicia having a plurality of elements, means for positioning said indicia in response to movement of said servomotor means, a platen positioned for printing cooperation with said indicia, holder means for holding a sheet between said indicia and platen, a type indicia aligner mechanism for selectively aligning the elements of said indicia, a platen control device for urging said platen against the sheet and said type indicia, and indexing means for automatically advancing the sheet through a preselected increment responsive to the actuation of said platen.

10. In apparatus of the class described, the combination comprising: force sensitive electro-responsive means for producing an electric signal in response to force applied thereto; an electric null system electrically connected to said means for receiving a signal therefrom, and including a balance signal device for introducing a countersignal into said system, said device including signal balance responsive means for governing the balance signal; and a printing device for use with a print sheet and including: type indicia having a plurality of elements, indicia drive means operatively associated with said balance responsive means, a type indicia element aligner for selectively aligning said elements, means for urging the print sheet against said indicia, and means responsive to residual force upon said force sensitive means for adjusting said indicia to zero.

11. In apparatus of the class described, means responsive to a physical quantity; an electrical device associated with said means for measuring said quantity and producing a variable electrical parameter in response to the value of such quantity; an electric null system operatively connected to said device and responsive to said parameter, said system including a servo element and a balance element for introducing a balance signal into said system, the servo element governing said balance element and in turn being governed in response to the degree of balance between said parameter and signal; a fine indicia element; a coarse indicia element mechanically separate from said fine element; and separate self-synchronous repeater systems, each having a transmitter and a receiver, for operatively interconnecting said coarse and fine indicia elements with said servo element, the transmitters of said system being rotatable in response to said servo element and associated with each other for rotation at a preselected speed ratio.

12. In apparatus of the class described, an electro-responsive element; means operatively connected with said element for producing an electrical parameter in response to a physical change of said element caused by the action of a physical quantity; a null system in electrical

connection with said means and including a servo element operable in response to the parameter; a fine indicia element; a coarse indicia element mechanically separate from said fine element; and separate self-synchronous repeater systems, each having a transmitter and repeater, for operatively interconnecting said coarse and fine indicia elements with said servo element.

13. In apparatus of the class described, the combination comprising: weighing cell means including stress receiving column means carrying electrical resistance type strain gauge means bonded thereto for use with a source of electric energy of preselected carrier voltage frequency, the amplitude of which is responsive to stress applied to said column means; a null circuit for balancing a voltage signal from said cell means against a countersignal and including a servomotor operative in response to the difference between said signals; an electric viscous dampening circuit electrically associated with said null circuit and operative by said servomotor; an electric integration-differentiation circuit electrically associated with said system for minimizing the effects of random acceleration loads upon said cell means; coarse and fine stress indicia elements operative by said servomotor; a printing mechanism actuatable by a print motor for printing upon a sheet certain indicia upon said elements; manual control means for the motor; a movable holder for the sheet adapted for movement relative to said printing mechanism for printing upon different portions of the sheet, said holder being movable to an inactive position relative to said mechanism; holder indexing means for advancing said sheet responsive to actuation of the print motor; means for rendering said motor inoperative when said holder is in an inactive position; and means responsive to residual stress upon said cell means for introducing a tare adjustment to said indicia elements.

14. In apparatus of the class described, weighing cell means having stress receiving means associated with strain gauge means for controlling an electrical parameter in response to stress applied to said cell; an electric circuit in which said strain gauge means is connected including means for measuring an output signal of such circuit, such signal being responsive to the electrical parameter, a warp compensator in said circuit for adjusting such output signal thereof to be linearly proportional to weight; an indicator operative in response to such output signal; a tare compensator element in said circuit for adjusting the output signal therefrom and hence said indicator for tare; a stop-run control electrically connected in said circuit for arresting said indicator at indicated weight; electrical dampening and integration means associated with said circuit; means for governing said last named means for controlling the degree of dampening and integration; a weight digital printer having type indicia elements; means for controlling said indicia elements in response to the output signal of said cell means as measured in said circuit; and a temperature compensator element electrically associated with said circuit and cells for automatically adjusting the circuit output signal for ambient temperature differences at the cell means and indicator.
